UNITED STATES PATENT OFFICE.

ALFRED H. DYSON, OF MONTCLAIR, NEW JERSEY, ASSIGNOR, BY MESNE ASSIGNMENTS,
TO WESTERN ELECTRIC COMPANY, INCORPORATED, A CORPORATION OF NEW YORK.

SEMI-AUTOMATIC TELEPHONE-EXCHANGE SYSTEM.

1,232,250.

Specification of Letters Patent.

Patented July 3, 1917.

Application filed September 8, 1915. Serial No. 49,524.

To all whom it may concern:

Be it known that I, ALFRED H. DYSON, a citizen of the United States, residing at Montclair, in the county of Essex and State of New Jersey, have invented certain new and useful Improvements in Semi-Automatic Telephone - Exchange Systems, of which the following is a full, clear, concise, and exact description.

This invention relates to telephone exchange systems, and particularly to semi-automatic telephone exchange systems.

An object of the invention is to provide a telephone system in which a temporary call circuit is automatically extended from a calling subscriber to an idle operator, the number of said calling subscriber being simultaneously and automatically registered on a register sender at such operator's position, and in which automatic switches are directly controlled in accordance with such registration to establish a talking circuit between the calling subscriber and an inter-office trunk, which talking circuit is independent and apart from the position of the operator who answered the call.

Another object of the invention is to provide a telephone system in which connection is established between a calling and a called subscriber's line through and by means of district and office switches which are restored when the talking circuit between the lines is established.

Still another object of the invention is the provision of interoffice trunks which are accessible to a plurality of operators' positions, and to complete a talking circuit between the calling and called subscribers by directly operating switches at the ends of the trunk, one switch operating in the direction of the calling line and the other in the direction of the called line.

A still further object of the invention is to provide an automatic telephone exchange system in which the numbers of both the calling and called subscribers are registered at the operator's position to directly control switching apparatus for establishing talking connection between said calling and called subscriber.

In the drawings—

Figure 1 shows the circuits of the primary line switch and of the associated allotter,

Fig. 2 shows the circuits of the secondary line switch and of the associated allotter; 55

Fig. 3 shows the circuits of the district selector switch;

Fig. 4 shows the circuits of the recorder allotter;

Fig. 5 shows the circuits of the sectional recorder for recording the numbers of the substations as calling substations;

Fig. 6 shows the circuits of the district and office keys for recording the numbers of substations as called substations; 65

Fig. 20 is a key showing how the above described drawings are to be arranged to show the complete circuit layout;

Fig. 21 is a perspective view of a cross-bar line switch of the type shown in Figs. 1 and 2. This line switch is similar in type to the structure described in patent to John G. Roberts, No. 1,143,998, issued June 22, 1915.

Fig. 22 is a perspective view of the allotter shown in Figs. 1 and 2;

Fig. 23 is a perspective view, partly in section, of the allotter shown in Fig. 4;

Fig. 24 is a perspective elevation and Fig. 25 is a plan view of the recorder shown in 5 Fig. 5;

Fig. 26 is a sectional view of the line 25-25 of Fig. 25, showing the method of driving the arm of the recorder.

The mechanical structure of the switches 10 indicated in Figs. 3, 13, 14, 15, 16, 17, 18 and 19, is similar to that shown in Patent No. 1,128,696.

Cross-bar line switch.

15 The line switch used in this system is shown diagrammatically in Fig. 1 and in perspective elevation in Fig. 21. The terminals are arranged in the usual panel form, the ends of the terminals 106, 107, 108 and 20 109 and 120, 121, 122 and 123 protruding from the bank as shown. The terminals 106 to 109 inclusive are connected together but insulated from each other by the pin 124 of insulating material. The terminals 106 to 25 109 and 120 to 123 inclusive are arranged in horizontal groups, each horizontal group having individual thereto the horizontal rotatable rod 125. Each rod 125 has extending outwardly therefrom and over each 30 group of terminals, as above noted, a plurality of members 126. At the end of each rod 125 is an armature 127 operated by a double wound relay 101. The armature 127 is normally held in retracted position by a 35 spring 128, one end of which is fastened to an extension 129 of the armature, and the other end being fastened to the frame of the terminal bank in any convenient manner. At the outer end of the extension 129 is a 40 roller 130 of insulating material contacting with the end of a contact spring 131 which is connected by means of a block of insulating material 132 to a second contact spring 133. The energization of the relay 101 45 causes the attraction of the armature 127, with the consequent lifting up of the contacts 131 and 133 into engagement with the contact springs 134 and 135 respectively.

Vertical rods 136 are provided, one for 50 each vertical group of contacts 106 to 109 and 120 to 123 inclusive, and each rod 136 is provided with a flexible member 137, one of these members being provided for each 55 horizontal group of terminals 106 to 109 and 120 to 123 inclusive. The lower end of each of these rods 136 is provided with an armature 138. Each of the rods 136 has individual thereto a relay 110. Connected in the energizing circuit of relay 110 is a pair 60 of contacts 139, 140, normally in engagement with each other, but when the relay 110 is energized a projection 141 on the armature 138 moves into engagement with the contact 65 spring 139 and moves the same upwardly out of engagement with the contact 140,

breaking the energizing circuit for the relay 110.

70 Armature 138 is normally held in a retracted position by a spring 142 fastened one end to the armature and the other end to the frame in any convenient manner, the outward movement of said armature being limited by a pin 143. At the lower end of the armature is a depending projection 144 which, when the armature is attracted, moves 75 over behind a locking bar 145 held normally in an operated position by a spring 146. A double wound relay 113 is provided for moving the locking member 145 downwardly to release the armature 138, the end portion of 80 the locking member 145 acting as an armature for said relay 113. The extreme outer end of said locking member 145 contacts with but is insulated from the free end of a contact spring 147.

85 Relay 113 when energized moves the locking member 145 downwardly, and the outer end of said member moving into engagement with the contact spring 147 breaks the contact existing at this time between contact springs 148 and 149; also the engagement 90 existing between contact spring 147 and contact spring 150, and makes contact between 95 contact spring 147 and contact spring 151.

100 The operation of this device will be more 95 clearly understood if the same is read in connection with the circuit arrangement shown in Fig. 1 and with the allotter, the circuits of which are shown in Fig. 1 and the apparatus of which is shown in Fig. 22. It will be assumed that the arm 111 of the 105 allotter is in contact with the terminal of the allotter bank which is connected to the contact spring 139 of the relay 110 of the line switch. A circuit is therefore closed for the 110 relay 110 from battery, through the winding of said relay 110, contact springs 140, 139, the proper contact in the terminal bank of the allotter, arm 111, contact spring 150 operated by the relay 113, contact spring 110 147 to ground. The closure of this circuit energizes relay 110 which attracts its armature 138, rotating the vertical rotatable rod 136, moving the spring members 137 outward to the left, as viewed in Fig. 21, and in 115 operative relation to the vertical bank of contact springs 106 to 109 and 120 to 123 inclusive, preselecting in this manner the vertical group of contacts in anticipation of the next call to be sent over the line.

120 A call coming in over the line conductors 103 and 104 of a plurality of subscribers, may pass through any one of the line relays 101 individual to any of the horizontal groups of contacts 106 to 109 and 120 to 123 inclusive. I will assume that the call coming in passes through the line relay 101 individual to the upper horizontal group of contacts shown in Fig. 21. Relay 101 therefore energizes, attracting its armature 127 125 130

and moving the arm 126 downwardly into engagement with the bank of contact springs above noted. There are as many extending arms 126 for each horizontal rotatable rod 125, as there are vertical groups of contact springs, but the arms 126 are so arranged with relation to the groups of contact springs that only that group of springs will be operated with which the member 137 has been moved into engagement. The extending arm 126 moving downwardly, first moves into engagement with the member 137, and both these members are sufficient to cause the movement of contact springs 106 to 109 inclusive to engage with contact springs 120 to 123 inclusive. The movement of armature 127 has also caused, through the medium of the insulating member 130 carried thereby, the engagement of contact springs 131 with 135 and 133 with 134, for a purpose which is described in connection with the operation of the system. The closure of the contact springs 106 to 109 inclusive with the contact springs 120 to 123 inclusive, respectively, establishes a circuit from battery, one winding of the relay 113, and arm 111 and contact of the allotter bank of contacts, contact spring 121, contact spring 107, the second winding of line relay 101 to ground, energizing said relay, which attracts the outer end of the movable locking member 145, moving the inner end thereof out of engagement with the member 144 of the armature 138, allowing the spring 142 to move said armature 138 to its retracted position in engagement with the stop pin 143, thus causing the rotation of the vertical rotatable arm 136, which carries with it all unengaged members 137. The members 137, however, being flexible, the one which is in engagement with the operated springs 106 to 109 and 120 to 123 inclusive remains in engagement therewith until the release of the line relay 101, which only occurs when connection has been established from the district selector switch shown in Fig. 3 with the calling subscriber through the "A" final switch, shown in Fig. 15. The attraction of the outer end of the movable locking member 145 has also, by the engagement with the extreme outer end thereof with the contact spring 147, broken the engagement between off-normal springs 148 and 149, 150 with 147, and the engagement of springs 147 with 151. The breaking of the contact between the off-normal springs 148 and 149 prevents any other subscriber of the group to which the calling subscriber belongs from coming in and appropriating the particular group of springs now in use. The breaking of the engagement between contact springs 147 and 150 prevents the reenergization of the relay 110, while the engagement of the contact springs 147 and 151 closes a path in a lock-in circuit for the relay 117 of the allotter

shown in Fig. 22, keeping the same locked up until the calling subscriber has been connected with, as above described.

The line switch shown in Fig. 2 is practically identical with the line switch above described, differing only in the arrangement of the operating relays.

The line switch allotter.

The allotter shown schematically in Fig. 1 is illustrated in perspective in Fig. 23. It comprises a circular plate member 152 to which is attached a U-shaped bearing member 153. Both the circular member 152 and U-shaped member 153 provide bearings for a shaft 154, to the lower end of which shaft is insulatingly mounted an arm 111 consisting of a plurality of contact members. At the upper end of this shaft 154 and beneath the U-shaped member 153 is fastened a circular plate 155 having a projecting finger 156 as shown.

Loosely mounted on the upper end of the shaft 154 is a hollow ratchet 157. Mounted in the ratchet 157 is a spring-driving member 158, one end of which is attached to the shaft 154, and the other end to the ratchet 157. A holding pawl 159 meshes with the ratchet 157, being held in engagement therewith by a spring 160. The pawl 159 is pivotally mounted on a member 161, which is in turn pivotally mounted on the shaft 154. An extending arm 162 of the member 161 has attached thereto one end of a spring 163, the other end of said spring being fastened to the U-shaped member 153 in any convenient manner, the spring holding the member 161 over into engagement with the limiting stop 164, also mounted in the U-shaped member 153. This is the condition of the apparatus when the tension of the spring 163 is greater than the tension of the driving spring 158.

The movement of the member 161 over into engagement with the limiting stop 164 allows the contact spring 165 to move into engagement with the contact spring 166, closing the circuit for the winding magnet 167. The winding magnet 167 attracting its armature 168, the pawl 169, which is pivotally mounted on said armature 168, moves into engagement with the ratchet 157, moving the same in a clockwise direction, as viewed in the figure, through a distance of one tooth, in which position the ratchet is held against return movement by the pawl 159. The armature 168 has a rearwardly extending arm 170 integral therewith. On the extreme end of this arm 170 is a pivotally mounted arm 171, in the outer end of which is a notch 172 engaging with a spring member 173 working between the limiting stops 174, which stops are fastened to the U-shaped member 153 in any convenient manner. The arm 171 is held yieldingly in en-

gagement with the spring member 173 by a spring 175. As the armature 168 is attracted, an insulating button on the arm 171 moves contact spring 176 into engagement with contact spring 177, insuring the continuance of the energizing circuit for the winding magnet 167 from battery, contact spring 178, contact spring 179, contact springs 177 and 176 to ground, irrespective of what may happen at this stage of the operation to the contact springs 165 and 166. As the armature continues to be attracted, the arm 171 moves the spring member 173 into engagement with the outer limiting stop 174, when the arm 171 moves outwardly against the tension of the spring 175, and the outer end of the spring member 173 rides up on the cam face 180 until the armature 168 has reached the extreme limit of its travel, at which time spring member 173 falls over into engagement with the inner limiting stop 174 breaking the contact existing between contact springs 178 and 179. As the armature 168 retracts, the inner face of the cam 180 is in engagement with the contact spring 173 insuring that the contact between springs 178 and 179 remains broken until the armature 168 is fully retracted, at which time the spring 173 has ridden over the inner cam face of 180 and back into engagement with the slot 172. This alternate energization and deenergization of winding magnet 167, with the consequent stepping around of the pawl 157 and winding up of the spring 158, continues until the tension in spring 158 is greater than the tension in spring 173, when the member 161 is moved over into engagement with the limiting stop 245, breaking the engagement of contact spring 165 with contact spring 166.

The shaft 154, carrying the bank of spring arms 111, will rotate under the influence of the driving spring 158 until the projection 156 on the member 155 strikes against the extension 182 of the armature 183 of either of the double wound magnets 117 that are mounted on the supporting member 152. Should all of the magnets 117 be energized and therefore the projection 182 out of the path of the projection 156, then the master stepping magnet 184 will be deenergized and the projection 185 on its armature 186 will lie in the path of the projection 156, and will therefore stop the rotation of the member 155. This will be more clearly apparent from an inspection of Fig. 1, where, if we assume that both the relays 117 are energized, no energizing circuit for the master stop magnet 184 exists, but if any one of the relays 117 is deenergized a circuit for master stop magnet 184 may be traced from battery, winding of the magnet 184, right armature and back contact of the deenergized relay 117, right armature and front

contact of the energized relay or relays 117 to ground.

We will assume that the direction of rotation of the member 155 is in a clockwise direction as indicated by the arrow, and that the projection 156 is in engagement with the projection 182 of the armature 183 of the outer double wound relay 117, so that the arm 111 has its contact springs in engagement with the group of contacts in the bank 112, corresponding to the relay 117. Also that this is the proper position for the relay 110 of the line switch shown in Fig. 21 to be energized to rotate the vertical arm 136 into position to preselect a vertical group of contacts 106 to 109 and 120 to 123, inclusive, so that one of said group of contacts will be definitely selected when the proper line relay 101 is energized by the removal of the calling subscriber's receiver from its switchhook. When the line switch contacts have been closed to extend the line of the calling subscriber from the line switch shown in Fig. 1 to the line switch shown in Fig. 2, the relay 117, with which the projection 156 of the member 155 is in engagement, will be energized, releasing the member 155, which under the influence of spring 158 rotates in a clockwise direction, continuing its rotation until stopped by the projection 182 of the armature 183 on the first deenergized relay 117, in this case the most rearwardly shown in Fig. 23.

The allotter shown in Fig. 2 is practically identical with the allotter above described differing slightly in the number and arrangement of the operating relays.

Recorder allotter.

In Fig. 22 is shown the allotter used in connection with the circuit arrangement shown in Fig. 4. A plate 200, having fastened thereto a U-shaped member 201, provides bearing surfaces for a rotatable shaft 202 which carries at its lower end an arm 203 consisting of a plurality of contact springs 205 to 208 inclusive, and at its upper end a winding mechanism identical with the winding mechanism described in connection with Fig. 23. Near the upper end of the shaft 202 is a rotatable arm 204 which rotates in a clockwise direction, as viewed in the figure. A plurality of magnets 209 are provided equal in number to the number of calling subscribers in a group, the subscribers in the system shown being arranged in groups of ten, although this number may be varied to suit existing conditions. When any one of the relays 209 is energized it moves a pair of contacts 210 and 211 into engagement with a pair of contacts 212 and 213 respectively. Near the lower end of the shaft is fastened a ratchet 215.

In operative relation to this ratchet 215

is a release magnet 214, to the armature of which is fastened a holding pawl 221 normally in engagement with the ratchet 215 and preventing the rotation of the shaft 202.

5 When the district selector switch, shown in Fig. 4, moves into its third position to connect the operator's set thereat with the calling subscriber, a circuit will be closed, for the relay 209 individual to the calling subscriber of the group, from battery, winding of the relay 209, contacts 216 of relay 217, conductor 218, lower right and upper left contacts of 219, conductor 242, upper right and left contacts of 236 to ground, energizing the relay 209 which attracts its armature, and moving a projection 220 thereon into the path of rotation of the outer end of the arm 204. It also moves contact springs 210 and 211 into engagement with contact springs 212 and 213 respectively, closing at the contact springs 210 and 211 an energizing circuit for the release magnet 214, which may be traced from battery, winding of said magnet 214, contact springs 210 and 212, lower armature and back contact of relay 217 to ground, energizing said release magnet and moving pawl 221 out from engagement with the ratchet 215, allowing the shaft to rotate until brought to rest by the extension 220 of the energized relay 209 contacting with the outer end of the arm 204, and stopping the shaft 202 with the contact springs 203 in engagement with the proper set of contacts in the bank 222, 35 the contacts 207 and 208 closing a break point in a circuit leading to the release magnets 309 of the recording device, shown in Figs. 5, 24, 25 and 26, and the contacts 205 and 206 closing break points in a circuit 40 leading from battery through the magnet 118, shown in Fig. 1, to connect the calling subscriber with the recording device to cause the automatic recordation of the number of the calling subscriber.

45 Upon the deenergization of relay 209 the energizing circuit for the release magnet 214 is broken at the contact springs 210 and 212, allowing the pawl 221 to move into engagement with the ratchet 215, so that although the armature 220 is moved out of engagement with the outer end of the arm 204, the arm does not move owing to its being locked by the ratchet 221 until the energization of either the same or some other 55 relay 209.

The recorder.

The recording device for recording the number of the calling line is shown in Figs. 60 24, 25 and 26. It comprises two sector-shaped plates 343 and 344 spaced apart in any convenient manner, the upper plate 343 having mounted thereon five magnets 345 to 349 inclusive, the lower plate 344 having

the magnets 350 to 354 inclusive mounted thereon, the magnets 345 to 354 inclusive representing the ten digits. Each of the magnets has pivotally mounted in operative relation to the core thereof an L-shaped armature 319, the depending portion of which operates a pair of contacts 355 and 356, the horizontal portion operating to depress a vertically movable member 318 having bearings in the upper and lower plates 343 and 344 respectively, and being held normally in position with respect to the plates 343 and 344 by a spring 357, one end of which bears on the plate 343 or 344, as the case may be, and the other end abutting against a pin 358 passing through the vertically movable member 318. Intermediate the ends of the vertical movable member 318 is a projecting portion 317 for a purpose to be hereinafter described. A stationary shaft 359 is mounted, one end in the plate 343 and the other in the plate 344. Fastened to said shaft 359, in any convenient manner, as by a screw 360, is a hollow member 361, to which is fastened the outer end of a driving spring 362, the inner end of said spring 90 being fastened to the depending hub 363 of a ratchet wheel 315. Fastened to the ratchet wheel 315 is an arm 316. The ratchet wheel 315 and arm 316 are held in operative relation to the member 361 by a collar 364 95 fastened to the shaft 359 by the screw 365. The arm 316 carries at its outer end a pivotally mounted projection 366 which, when the arm 316 rotates in the direction of the arrow as shown in Fig. 25, is adapted to 100 strike against the projection 317 on the vertically movable rod 318 of any of the magnets 345 to 354 inclusive, thereby stopping the arm 316 in such position.

In the normal position of the arm 316, as shown in Fig. 25, the off-normal contacts 311 are closed, remaining in this position until one of the magnets 345 to 354 inclusive of each of the thousands, hundreds, tens and units recorders are energized, the magnets energized representing the digits of the calling subscriber's number, at which time a circuit will be closed through the contacts 355, 356 of the thousands, hundreds, tens and units recorders in series, as shown more clearly in Fig. 5, closing a circuit through release magnet 309, which attracts its armature 367, and moving the pawl 314 out of engagement with the ratchet 315 and also closing contacts 329. This energizing circuit 115 for release magnet 309 also passes through the off-normal contacts 311, and as soon as the arm 316 moves away from its normal position, the original energizing circuit for release magnet 309 is broken at 120 the off-normal contacts 311. As, however, the release magnet 309 must be fully energized before the release of the arm 316

- takes place, a supplementary energizing circuit is established for said release magnet, this circuit being from battery, through the winding of the release magnet, the contacts 5 329 (closed by the attraction of the armature 367), the contacts 331 on the arm 316 to ground. This energizing circuit for the release magnet will be maintained until the projection 366 on the arm 316 comes into 10 engagement with the projection 317 on the vertically movable rod 318, which rod has been moved to bring the projection 317 thereon into the path of movement of the projection 366 by the energization of any 15 one of the magnets 345 to 354 inclusive, the magnet energized representing one of the digits of the calling subscriber's number. Immediately the projection 366 comes into engagement with the projection 317, the 20 arm 316 is stopped and contact 331 broken, destroying the energizing circuit for the release magnet, and allowing the pawl 314 to move into engagement with the ratchet 315.
- 25 When the arms 316 moved from their normal positions, breaking the circuits for the off-normal contacts 311, they closed circuits at their respective contacts 320, such circuits extending to their associated sequence switches of the thousands, hundreds, tens or units registers. When the arms 316 are stopped by engagement with the projections 317 of the positioned rods 318, springs 332 are closed, a circuit being completed 30 through these contacts 322 in series for the relay 217, shown in Fig. 4, which in turn breaks the energizing circuit for the release magnet 214 of the allotter described above and shown in Fig. 22.
- 40 By reference to Fig. 11 it will be seen that when the thousands, hundreds, tens and units register sequence switches have moved into position 2, that a locking circuit will be established for the relays 400 45 to ground at the contacts 320 shown in Fig. 5. Also that a circuit will be established from battery for the stepping magnet 334 to ground at the left armature and front contact of the relay 400. The stepping magnet 334 energizing, attracts its armature 368, and the pawl 369, pivotally mounted thereon, moves into engagement with the ratchet 315, stepping the arm 316 back toward its 50 normal position the distance of one tooth 55 on the ratchet 315, the ratchet being prevented from moving outward again by the pawl 314 on the release magnet 309. As the stepping magnet 334 energizes, the outer end of backward extension 370 of the armature 368 moves upward, as viewed in 60 Fig. 25, carrying therewith the pivoted member 371 having a notch and cam on its extreme end. The pivoted member 371 is held 65 to the right, as viewed in Fig. 25, by the

spring 372, with the notch at the extreme 65 end in engagement with a spring lever 373, which is placed in operative relation to but insulated from one of the spring contact members 374.

The original energizing circuit for the 70 stepping magnet 334 went to ground at the left armature and front contact of relay 400, and also through the upper and lower left contacts of 401, as well as through both contact springs 374. As the sequence switch 75 402 leaves its second position and until it reaches its third position, the original energizing circuit for stepping magnet 334 is broken at both the upper and lower left contacts of 401. However, as the pivoted 80 member 371 moves upwardly, a projection 375 thereon, of insulating material, closes contact springs 376 so that irrespective of what happens to the original energizing circuit of the stepping magnet, a circuit will 85 be maintained therefor through one of the contact springs 374, contact springs 376 to ground.

As the armature 368 approaches its extreme limit of travel, the member 371 has 90 forced the spring member 373 upwardly and into engagement with a limiting stop 377. Further movement on the part of the armature 368 causes the pivoted member 371 to move outwardly, the cam surface on 95 the extreme end thereof riding up on the spring member 373 until, when the limit of movement of armature 368 is reached, spring member 373 slips off the upper portion of the cam face and onto the lower portion, 100 breaking the contact existing at contact springs 374. The breaking of the contact existing between the springs 374 breaks and keeps broken the energizing circuit for stepping magnet 334 until the armature 368 105 thereon has been fully attracted.

As the armature 368 approaches its retracted position the spring member 373 rides up on the lower cam surface, on the extreme end of pivoted member 371, and 110 spring member 373 moves into engagement with a limiting stop 378. When the limit of return movement of the armature 368 is reached the spring member 373 will have 115 ridden over the lower face of the cam and into the slot, the mechanism resuming its normal position.

For each step of the arm 316 backward, the sequence switch corresponding thereto and shown in Fig. 11 will be moved forward, and in addition, when the arm 316 reaches its normal position, the sequence switch 400 will take one additional step. As the stepping circuit for the magnet 334 is only completed in the second position of 120 the sequence switch 400, the sequence switch will have been moved two more positions 125 than the number represented by the ener-

gized one of the digit magnets 345 to 354 inclusive.

The recording device has been shown with two groups of magnets of five each to represent the ten digits, the magnets being arranged five on the top plate 343 and five on the bottom plate 344. This arrangement has only been adopted for the purpose of saving space, and it will, of course, be apparent that it would be perfectly feasible to have arranged the magnets all on the same plate or to have even grouped them differently on the same or on any number of plates.

15 *General description and operation.*

Briefly a description of the operation of a call when both subscribers are located in the same exchange is as follows: The calling subscriber removes his receiver from the hook. The allotter, shown in Fig. 1, places at the disposal of the subscriber the next idle set of trunks leading to the secondary line switch shown in Fig. 2. The allotter at 25 the secondary line switch places at the disposal of the subscriber the next idle trunk leading from the secondary line switch to the operator shown in Fig. 3. The call having been extended as far as the operator at 30 the district selector switch shown in Fig. 3, the selector sequence switch operates, and in the third position thereof the allotter shown in Fig. 4 operates to place the next idle set of recorders in position to record 35 the number of the calling subscriber's line. Also, in the third position of the apparatus at the district selector switch, a circuit is extended back to the primary line switch for the purpose of extending the line of the 40 calling subscriber through to the allotted recording device shown on Fig. 5, where the number of the calling subscriber is recorded and then automatically registered on the calling line register shown in Fig. 11.

45 When the district selector sequence switch moved into its second position the temporary call circuit was established from the calling subscriber to the operator, who ascertains from the calling subscriber the 50 number of the wanted subscriber and then depresses the number keys shown in Figs. 6 and 7, recording thereby the district and office number and also the numerical number of the wanted subscriber, which numbers are automatically registered on the district and office registers shown in Fig. 10 and the numerical number register shown in Figs. 8 and 9. Upon the completion of the 55 registration of both the calling and called numbers, the sending device shown in Fig. 12 operates to control the operation of, first, the office selector switch shown in Fig. 13, and then in turn the local incoming switch shown in Fig. 18, the "A" final switch

shown in Fig. 15 to the calling subscriber, 65 and then the "B" local incoming switch shown in Fig. 19 and the final switch shown in Fig. 17, at which point the called subscriber is automatically rung and talking connection established between the calling 70 and called subscribers.

Upon the recordation of the calling subscriber the recorder shown on Fig. 5 returns to normal. Likewise, when the district and office number and the numerical number of the called subscriber is registered on the registers shown in Figs. 8 and 9, the keys shown on Figs. 6 and 7 return to normal. Upon the completion of talking connection between the calling and called subscribers, all the apparatus shown on Figs. 1, 2, 3, 4, 12 and 13 return to normal, and the only apparatus in use during a conversation between two subscribers is the apparatus shown in Figs. 15, 18, 13, 19 85 and 17.

For establishing a connection between a calling subscriber located in one office and a called subscriber located in another office, the operation is practically identical to that described above, except that the operator depresses a district and office key that will cause the selection, by the district selector switch, of an office selector switch leading to a trunk terminating in switches located 90 one at the calling office and the other in the called office.

The circuits and apparatus of the system will be best understood from a description of the operation of extending a call from a 100 calling to a called subscriber.

We will assume that subscriber 4342 wishes to talk with subscriber 5682 located in the same exchange. Under these circumstances the interoffice incoming switches shown in Figs. 14 and 16 will not be involved in the connection and need not be further considered at this time. Subscriber 4342 removing his receiver from the switch-hook establishes a circuit from battery, contacts 148 and 149 of the cross-bar line switch, lower winding of line relay 101, lower armature and contact of cutoff relay 102, conductor 103, through the subscriber's apparatus, back over line conductor 104, upper armature and contact of cutoff relay 102, to ground.

The line switch is in the condition described above, with relay 110 energized and a vertical series of contacts 106 to 109 and 120 to 123 inclusive selected by the rotation of the vertical rod 136 individual to said relay 110. The line switch allotter is also in the position described above with the projection 156 on the member 155 in engagement with the projection 182 of the armature 183 of the next idle magnet 117 and the contact arms 111 in engagement with the group

of contacts in the bank 112 individual to the magnet 117 and relay 110.

The line relay 101 operates, rotating the shaft 125, moving the projection 126 downwardly into engagement with the member 137 and causing the engagement of contact springs 106 to 109 with contact springs 120 to 123, respectively. The line relay 101 is, however, slow acting to the extent that various operations in the allotter and line switch take place before its armatures are attracted, as the cutoff relay 102 operates to cut off the substation of the calling subscriber from the line relay, when the upper armature of the line relay is fully attracted.

A circuit is now closed from battery, upper winding of relay 113, one of the contact springs of arm 111, terminal 112, conductor 116, terminals 121, 107, upper winding of line relay 101, to ground, momentarily energizing said relay 113, and providing a temporary locking circuit for the line relay 101. Relay 113, attracting its armature, closes a circuit from battery, left winding of relay 117, contact 105, arm 111, armature and front contact of relay 113, to ground, energizing said relay 117, providing a circuit from battery, right winding of relay 117, left armature and front contact thereof, conductor 116, contacts 121, 107, upper winding of line relay 101, to ground, this circuit acting as a locking circuit for both relay 117 and line relay 101, keeping the same locked up until the office selector 35 has been connected with the calling subscriber.

The energization of the relay 113 caused the opening of contacts 148 and 149, and the release of the armature 138 of the relay 110, by the depression of the locking member 145. Also, the energization of relay 117 caused the release of the member 155. The shaft 154, therefore, rotates in the direction of the arrow shown in Fig. 23, carrying with it the arm 111, until the projection 156 on the member 155 comes into engagement with the stop 182 on the armature 183 of the next idle relay 117, or, should all the relays 117 be occupied, then into engagement with the stop 185 on the armature 186 of the master stop magnet 184.

The energization of the relay 117 closes a circuit from battery (Fig. 2) through contacts 148 and 149 of the secondary line switch, left winding of secondary line relay 114, contacts 115, conductor 119, left armature and front contact of relay 117, conductor 116, contacts 121, 107, upper winding of line relay to ground. The closure of this circuit energizes secondary line relay 114, and the right armature thereof breaks the above traced circuit at contact 115, establishing however, before the breaking of this circuit, a circuit from battery, through the right winding of line relay 114, right armature,

contact 115, and the circuit above traced which extends through the left winding of said line relay. As in the case of the primary line switch, the relay 110 is energized over circuit from battery, said relay 110, 70 armature and back contact thereof, contact and arm 111, of the allotter, armature and back contact of relay 213 to ground, moving trunk contacts 187, 188, 189 and 190 into engagement with contacts 191, 192, 193, 194, to 75 extend the line of the calling subscriber from the secondary line switch to the district selector switch shown in Fig. 3.

The circuit for the relay 213 is established from battery, through said arm 111 and contact 112 of the allotter, conductor 195, upper left and lower right contacts of 223 to ground, energizing the relay 213 and establishing a circuit for the relay 117 from battery, left winding thereof, contact 112 and arm 111 of the allotter, armature and front contact of relay 213 to ground, and a locking circuit for the relay 117 is established over the conductor 195 at the left armature and front contact of said relay 117 upon the deenergization of the relay 213. Upon the engagement of trunk contacts 187, 188, 189 and 190 with contacts 191, 192, 193 and 194 respectively, a circuit is established from battery, relay 224, upper right and left contacts of 225, conductor 196, trunk contacts 192, 188, conductor 197, trunk contacts 121, 107 of the primary line switch, upper winding of line relay 101 to ground. Relay 224 energizes and at its front contact and right armature closes a circuit for the motor magnet of sequence switch 226 over the circuit from battery, winding of motor magnet 227, upper left contact of 228, conductor 229, front contact and right armature of 224 to 95 ground, sending the sequence switch out of position 1 and into position 2.

In position 2 the operator's set 230 is connected at the upper right and left contacts of 231 and lower right and left contacts of 232 with the calling subscriber over the temporary call circuit comprising the conductors 198 and 199, trunk contacts 194, 190, 193, 189 of the secondary line switch, conductors 94 and 97, trunk contacts 123, 109, 122, 108 of 100 the primary line switch conductors 103, 104. The operator finds out from a calling subscriber the number of the line wanted. In the meantime a circuit is closed from relay 233, lower right and upper left contacts of 120, 234, conductor 235, lower left contact of 236 to ground, energizing said relay 233 and establishing at its left armature and front contact a circuit over the conductor 237 for the motor magnet of sequence switch 238 of 125 the allotter, moving the sequence switch out of position 1 and into position 2.

As the allotter sequence switch moves into position 2, the circuit for the relay 233 is broken at 234, and a circuit is closed at the 130

back contact and left armature of said relay 233 for the district selector sequence switch 226, moving the same from position 2 and into position 3, said circuit being as follows: battery, motor magnet of sequence switch 226, conductor 227, lower right contact of 228, conductor 239, upper left and lower right contacts of 240, conductor 241, back contact and left armature of relay 233.

10 When the district selector switch reaches its third position a circuit is closed for the relay 209 of the allotter, from battery, winding of said relay 209, contacts 216, conductor 218, lower right and upper left contacts of 219, conductor 242, upper right contact of 236 to ground. Relay 209 is energized, attracting its armatures, and at its front contact and right armature closes a circuit for the release magnet 214 as follows: battery, 15 winding of release magnet 214, front contact and right armature of relay 209, conductor 243, back contact and lower armature of relay 217, to ground.

20 The energization of release magnet 214 allows the arms 204 to revolve in a clockwise direction, and when the contact arm 203 is stopped by the armature of the relay 209, a circuit is closed from battery, relay 118, lower armature and front contact of line 25 relay 101, trunk contacts 106, 120, conductor 99, trunk contacts 187, 191, conductor 98, lower right and left contacts of 225, conductor 244, upper left and lower right contacts of 245, conductor 246, contact springs 30 205, 206, contacts 211 and 213, to ground.

35 The energization of the relay 118 closes two circuits at the recorder shown in Fig. 5 to record the number of the calling subscriber on said recorder, the circuits being as follows: battery, winding of relay in the thousands recorder 300, conductor 304, upper armature and contacts of relay 118, conductor 305, through the winding of the relay in the hundreds recorder 301 to ground; from battery through the winding of the relay in the tens recorder 302, conductor 306, lower armature and contact of relay 118, conductor 307 through the winding of the relay in the units recorder 303, 50 to ground.

The other contact springs 207, 208 on the arm 203 of the allotter, shown in Fig. 4, close a break point in a circuit, which includes the contacts 308 operated by the relays in the thousands, hundreds, tens and units recorders, respectively. This circuit includes the release magnets 309 of the thousands, hundreds, tens and units recorders, and may be traced as follows: battery, 55 release magnet 309, conductor 310, off-normal contact 311, conductor 312, contact springs 207, 208, of the allotter, conductor 313, contacts 308 to ground. The completion of this circuit energizes the various release magnets 309 of the thousands, hundreds,

tens and units recorders, withdrawing pawls 314 from engagement with their respective ratchets 315, allowing the arms 316 to rotate in an anti-clockwise direction until brought to rest by the projections 317 on the vertically movable members 318 operated by the armatures 319 of the relays corresponding to the various digits in the calling subscriber's number.

When the arm 316 left its normal position and opened the off-normal contact 311, the energizing circuit for the release magnet 309 was maintained over a circuit from battery, through said release magnet 309, contacts 329, conductor 330, contacts 331 to ground. This circuit is maintained until the arm 316 strikes the projection 317, on the vertically movable member 318, operated by the armature 319 of the relay corresponding to the digit of the calling subscriber, 85 when the circuit is broken at contact 331. The arm 316, when it contacts with the projection 317, closes a break point in a circuit at contacts 332 which may be traced from battery, the relay 217, conductor 383, the contacts 332 of the thousands, hundreds, tens and units recorders in series to ground, energizing the relay 217, which relay attracts both its armatures, and its upper armature breaks the circuit of the magnet 209 at the 95 contact 216. The circuit of the release magnet 214 is also broken at the right armature and front contact on the relay 209 and at the lower armature and back contact of the relay 217. The armature of the release magnet is therefore retracted and the pawl 221 engages the ratchet 215, stopping the arm 100 204 of the allotter.

The energization of relay 217 completes also a circuit for relay 233 extending from grounded battery, winding of relay 233, lower right and left contacts of 234, lower armature and front contact of relay 217 to ground. Relay 233 upon energization, completes a circuit at its left armature and front contact to move sequence switch 238 out of position 2 and into position 3. When each arm 316 left its normal position it opened the off-normal contact 311 and closed a contact 320, closing in this manner a plurality of 115 circuits, one from each of the recorders. Contact 320 of the thousands recorder closes a circuit which may be traced from battery, relay 400 of the thousands register, upper and lower right contacts of 401 of the thousands register, conductor 321, upper left and lower right contacts of 247, conductor 322, contact 320 of the thousands recorder to ground. Contact 320 of the hundreds recorder closes a circuit which may be traced from battery, relay 400 of the hundreds register, upper right and lower right contacts of 401, conductor 323, upper left and lower right contacts of 248, conductor 324, off-normal contact 320 of the hundreds recorder 120 125 130.

to ground. Contact 320 of the tens recorder closes a circuit which may be traced from battery, relay 400 of the tens register, upper and lower right contacts of 401, conductor 5 325, upper left and lower right contacts of 249, conductor 326, contact 320 to ground. Contact 320 of the units recorder closes a circuit which may be traced from battery, relay 400 of the units register, upper and 10 lower right contacts of 401, conductor 327, upper left and lower right contacts of 250, conductor 328, contact 320 to ground.

The motor magnets of sequence switch 402 of the thousands, hundreds, tens and units 15 registers are energized in parallel with the relays 400, the sequence switches moving from position 1 to position 2. The relay 400, which energizes on the completion of its circuit (above traced), attracts its armatures 20 and is held energized after the sequence switch leaves its first position and until it reaches its second position over a circuit which may be traced from battery, relay 400, right armature and front contact thereof, a 25 spring of the sequence switches to ground. In position 2 of the sequence switches of the thousands, hundreds, tens and units registers, circuits may be traced as follows:

From the thousands register: battery, 30 stepping magnet 334 of the thousands recorder, conductor 335, lower right and upper left contacts of 251, conductor 336, lower and upper left contacts of 401, left armature and front contact of relay 400 to ground.

35 From the hundreds register: battery, stepping magnet 334 of the hundreds recorder, conductor 337, lower right and upper left contacts of 252, conductor 338, lower and upper left contacts of 401 of the hundreds 40 register, left armature and front contact of relay 400 to ground.

From the tens register: battery, stepping magnet 334 of the tens recorder, conductor 339, lower right and upper left contacts of 45 253, conductor 340, lower and upper left contacts of 401 of the tens register, left armature and front contact of relay 400 to ground.

From the units register: battery, stepping magnet 334 of the units recorder, conductor 50 341, lower and upper left contacts of 254, conductor 342, lower and upper left contacts of 401 of the units register, front contact and left armature and front contact of 55 relay 400, to ground.

The sequence switches of the thousands, hundreds, tens and units registers now step forward as described in connection with the recorder.

60 While the above has been taking place the operator has asked for and received the number of the called subscriber, which we have assumed to be 5682. The operator depresses keys in the thousands, hundreds, tens and 65 units bank (and shown in Fig. 7), corre-

sponding to the numeral number of the called subscriber's number, in this instance 5 in the thousands, 6 in the hundreds, 8 in the tens, and 2 in the units. Also she depresses one of the keys, as 379, shown in Fig. 6, denoting the district and office in which the calling subscriber is located, in this instance the same exchange in which the call originated. Both the district and office key and the keys representing the numerical number of the called subscriber are held in their depressed position by the locking relays 380 and 381, respectively. In the meantime, also, the sequence switch 403 for the district and office registers and numerical registers has been moved from position 1 to position 2 over the following circuit: battery, motor magnet of sequence switch 403, 70 lower left contact of 404, conductor 405, lower right contact of 255 to ground. 75

When the sequence switch reaches its second position a circuit is closed from battery, resistance 406, upper right contact of 407, lower right contact of 408, energizing winding of 409, conductor 410, contacts of the 80 district and office button 379, conductor 382, energizing winding of relay 411, conductor 412, lower right contact of 413, conductor 414, lower left contact of 415, conductor 416, energizing winding of relay 417 to ground. 85 The relays 409, 411 and 417 are energized in series and a locking circuit therefor is established which will be presently described.

The depression of the thousands key, which we assumed was No. 5, establishes a 100 circuit from battery, lower and upper right contacts of 418, energizing winding of relay 419, conductor 420, the depressed key No. 5 in the thousands register, conductor 421, energizing winding of relay 422, lower left contact of 423, conductor 424, lower right contact of 425 to ground. The relays 419 and 422 are energized in series, establishing locking circuits for themselves which will be 105 presently described.

The depression of the hundreds key, which we have assumed was key No. 6 in the hundreds register, establishes a circuit from battery, lower right and upper left contacts of 418, energizing winding of relay 426, 115 conductor 427, the depressed key No. 6 in the hundreds register, conductor 428, energizing winding of 429, upper right contact of 423, conductor 424, lower right contact of 425 to ground. Relays 426 and 429 energized over the last traced circuit established locking circuits for themselves, which circuits will be presently described.

The depression of the tens key, which we have assumed was key No. 8 in the tens register, establishes a circuit from battery (Fig. 9), upper left contact of 430, upper right contact of 431, energizing winding of relay 432, conductor 433, the depressed key No. 8, conductor 383 to ground. The relay 432 is 120 125 130

energized establishing a locking circuit for itself which will be presently traced.

The depression of the units key, which we have assumed to be the No. 2 key in the units register, establishes a circuit from battery, upper left contact of 430, conductor 434, lower left contact of 435, energizing winding of relay 436, conductor 437, the depressed key No. 2, conductor 384, to ground.

10 The relay 436 is energized and establishes a locking circuit for itself which will be presently traced.

The relays 417, 409, 411 of the district and office register and the relays 419, 422, 15 426, 429, 432 and 436 of the numerical registers are locked up over the following circuit: battery, conductor 438, locking winding of relay 436, conductor 439, conductor 440, locking winding of relay 432, conductor 20 441, locking winding of relay 429, conductor 442, locking winding of relays 426 and 419 in parallel, conductor 443, locking winding of relay 422, conductor 444, conductor 445, locking winding of relay 409, conductor 446, 25 conductor 447, locking winding of relays 411 and 417 in parallel, conductor 448, relay 256, upper left contact of 257, to ground.

The establishment of the locking circuit for the district and office and numerical registers energizes also the relay 256 (Fig. 3), which attracts its armature and closes a circuit from battery, motor magnet of sequence switch 226, conductor 227, upper right contact of 228, armature and front contact of 256, conductor 258, armature and front contact of the relays 449 of the thousands, hundreds, tens and units registers of the calling lines to ground, moving the sequence switch 226 from the third into the fourth position, 40 the relays 449 having been energized when their respective relays 400 were deenergized as a result of the return of the corresponding recorder arms to normal position. In the fourth position of this sequence switch 45 the following circuits are established.

Battery, key-restoring relays 380 and 381 in parallel, conductor 385, lower right and upper left contacts of 259, conductor 260, lower and upper right contacts of 257 to 50 ground, releasing the depressed keys of the district and office recorder and numerical recorder.

Battery (Fig. 12), motor magnet of sequence switch 500, upper left contact of 501, 55 conductor 502, upper right contact of 261 to ground, moving sequence switch from position 1 to position 2.

Battery, through a lamp 262, upper left and lower left contacts 261 to ground, lighting said lamp and indicating that the calling and called line numbers have been registered, which lamp remains lighted until the sequence switch returns to normal position.

A circuit is also established at this time 65 to move sequence switch 238 from its third to

its fourth position, this circuit extending from grounded battery, motor magnet of switch 238, lower right and upper left contacts of 800, lower right contact of 257 to ground. Sequence switch 238 remains in 70 position 4, which is one of its starting positions, the arrangement of this switch being such that its cycle of operation requires movement through only three positions.

When sequence switch 500 reaches its second position a circuit is closed from battery, relay 224, lower left and upper right contacts of 263, conductor 264, upper armature and back contact of the 0' counting relay (Fig. 12), the stepping relay 503, upper left contact of 504, conductor 265, lower right and left contacts of 266 to ground. The relay 224 attracts its armatures and at its right armature closes a circuit for the motor magnet of sequence switch 226 from battery, 85 motor magnet, conductor 227, upper left contact of 228, right armature and front contact of relay 224 to ground, moving the sequence switch 226 from the fourth into the fifth position. As sequence switch 226 left 90 its fourth position and until it reaches its sixth position, relay 224 is held energized over the following circuit:

Battery, winding of relay 224, lower right contact of 269, left armature and front contact of relay 224, lower and upper right contacts 263, conductor 264, upper armature and back contact of the 0' counting relay, stepping relay 503, upper left contact of 504, conductor 265, lower right and left contacts 100 of 266, to ground.

In the fifth position of sequence switch 226, the following circuits are established:

Battery, winding of relay 224, lower right and left contacts of 269, the "A" commutator, to ground. 105

Battery, winding of "up magnet" 270, upper right and left contacts of 271, right armature and front contacts of relay 224, to ground.

Battery, conductor 505, energizing winding of the 0 counting relay, conductor 506, top armature and front contact of the relay 411, conductor 450, lower right contact of 507, conductor 508, lower left contact 267, 115 conductor 268, armature and front contact of stepping relay 503, to ground.

The 0 counting relay, attracting its armature, closed a circuit for the 0' counting relay in parallel with the 0 relay, which circuit extends from conductor 506 through the energizing winding of the 0' counting relay, armature and front contact of the 0 counting relay, upper and lower right contacts of 510, to ground. The 0' counting relay is not energized, however, because of ground at the armature of stepping relay 503 being on conductor 506.

The "up magnet" being energized, moves the brush upwardly over the "A" commuta-

- tator. As the brush, in its movement, comes into engagement with the first segment of the "A" commutator, the ground from such segment, through lower left and upper right contacts of 269, to the left armature and front contact of relay 224, shunts out the stepping relay 503, which deenergizes, removing ground from the conductor 506, and allowing the 0' counting relay to energize over circuit, battery, conductor 505, the 0 and 0' counting relays in series, armature of the 0 counting relay, upper right contact of 510, to ground.

The 0' counting relay attracting its armatures, breaks at its upper armature the energizing circuit for the stepping relay 503, and at its lower armature and front contact establishes an energizing circuit for the sequence switch 500, through the upper right contact of 501, moving the sequence switch from its second into its fourth position, restoring the 0 and 0' counting relays.

The up magnet 270, being still energized, the brush continues its upward movement, and as it passes off the first segment of the "A" commutator, ground is taken off the energizing circuit for relay 224, which deenergizes at its right armature and front contact, breaking the circuit for the up magnet 270, and at the right armature and back contact closing a circuit to move sequence switch 226 out of its fifth and into its sixth position.

In the sixth position a circuit is closed from battery, trip magnet 272, upper left contact of 273, to ground, energizing said magnet and tripping the proper set of brushes into engagement with the bank of terminals.

In the sixth position of sequence switch 226 a circuit is closed from battery through relay 224, lower left and upper right contacts of 263, conductor 264, upper armature and back contact of the 0' counting relay, the stepping relay 503, upper left contact of 504, conductor 265, lower right and left contacts of 266 to ground, energizing the stepping relay 503, which attracts its armature closing a circuit from battery, conductor 505, the 0 counting relay, conductor 506, conductor 451, conductor 452, left armature and back contact of relay 453, conductor 454, upper right and lower left contact of 507, conductor 508, lower left contact of 267, conductor 268, armature and front contact of stepping relay 503, to ground. The relay 224 when energized in the sixth position of sequence switch 226 closed, at its right armature and front contact, a circuit to move sequence switch 226 from the sixth to the seventh position.

As before, the sequence switch 226, moving from one position to the next, breaks the original energizing circuit for the relay 224 at the lower left contact of 263, but an alter-

nate energizing circuit for said relay is provided at its left armature and front contact in the sixth and seventh position of said sequence switch.

In the seventh position of sequence switch 226 the following circuits are established:

A circuit through the 0 counting relay, as traced above.

A circuit for the relay 224.

A circuit for the "up magnet" 270, at the right armature and front contact of relay 224, moving the brush upward.

A circuit from the "B" commutator, upper left contact of 274, joining the energizing circuit of relay 224.

The brush, coming into engagement with the first segment of the "B" commutator, shunts out the stepping relay 503, allowing the 0' counting relay to energize in the manner above described, and breaking the energizing circuit for the relay 224 at its upper armature and back contact. When the brush passes off the first segment the relay 224 deenergizes, breaking, at its right armature and front contact, the circuit for the up magnet 270, and stopping the upward movement of the brush, which comes to rest in engagement with the first terminal of the group of contacts individual to said brush, and at its right armature and back contact completing a circuit to move sequence switch 226 from its seventh to its eighth position.

The energization of the 0' counting relay closed a circuit to move sequence switch 500 out of its fourth and into its seventh position.

In the eighth position of sequence switch 226 a circuit is closed from battery, relay 224, lower right and upper left contacts of 269, upper and lower right contacts of 223 to ground, moving the sequence switch out of position 8 and into position 9.

When the sequence switch 226 goes into the ninth position a circuit is closed from battery, winding of relay 224, lower left and right contacts of 269, "C" commutator to ground. Relay 224 attracts its armatures and at its right-hand armature closes circuit of up magnet 270 to move the brushes 275, 276 and 277 over the contact terminals 278, 279 and 280, respectively, of the bank of trunk terminals. As long as the trunk terminals 278, 279 and 280, over which the brushes 275, 276 and 277 move, are busy, ground will be found thereon to keep relay 224 energized during the time the brush is off the segments of the "C" commutator. When the brushes move onto the terminals of an idle trunk, the commutator brush being off the "C" commutator the relay 224 is deenergized at its right armature, deenergizing the up magnet 270, stopping the movement of the brush carriage with brushes 275, 276, 277 in engagement with the terminals 278, 279 and 280, respectively,

of the idle trunk, and at its right armature and back contact closing a circuit to move sequence switch 226 from the ninth into the tenth position.

5 In the tenth position, a circuit is completed from ground, lower right contact of sequence switch contact 261, conductor 521, lower left contact of 501, and motor magnet of sequence switch 500 to battery and ground, moving the sequence switch 500 into the eighth position.

In the tenth position of sequence switch 226 a circuit is closed from battery, relay 511, conductor 512, upper and lower left contacts of 513, conductor 514, terminal 278, brush 275, upper left and right contacts of 263, conductor 264, upper armature and back contact of the 0' counting relay, stepping relay 503, upper left contact of 504, conductor 265, lower and upper right contacts of 266, brush 276, terminal 279, conductor 515, lower right and left contacts of 516, to ground, energizing the relay 511, which attracts its armatures, and at its left armature and front contact closes a circuit from battery, winding of release control relay 517, upper left and right contacts of 518, left armature and front contact of 511, to ground. The release control relay 517 energizes, closing a circuit from battery, the motor magnet of sequence switch 519, lower left contact of 520, right armature and front contact of the release control relay, to ground, moving the sequence switch 519 from its first into its second position.

In this position a circuit is closed from battery, conductor 505, No. 2 counting relay, conductors 523, 459, lower armature and front contact of relay 409, conductor 460, upper left contact of 507, conductor 508, lower left contact of 267, conductor 268, armature and front contact of stepping relay 503, to ground, energizing the No. 2 counting relay.

45 When the sequence switch 519 moves into its second position a circuit is closed from battery, up-magnet 524, lower and upper right contacts of 518, left armature and front contact of 511, to ground, energizing said up-magnet to move the commutator brush over segments of the A commutator to select a brush leading from the office selector switch. In addition to the circuit through relay 511 and stepping relay 503, as above traced, an auxiliary circuit is provided from ground at the A commutator, upper and lower right contacts of 525, conductor 512, relay 511, to battery, shunting out the stepping relay 503 each time the brush moves into a segment of the commutator. As the brush passes over the A commutator segments, the stepping magnet 503 is shunted out allowing its armature to fall back, taking the ground off the conductor 523 and allowing the No. 2'

counting relay to be energized through the front contact and armature of the No. 2 counting relay and upper and lower right contacts of 510.

With each segment of the A commutator passed over by the brush, a pair of counting relays is energized until, when the 0' counting relay is energized, the circuit for the stepping relay 503 is broken at its upper armature and back contact. The brush, moving upwardly, passes off the segment of the A commutator, breaking the circuit of relay 511, which deenergizes, breaking at its left armature and front contact the circuit of the up-magnet 524, and makes at the left armature and back contact a circuit to move sequence switch 519 from its second into its third position. The trip magnet 527 is energized over circuit from battery, winding of trip magnet 527, upper right and lower left contacts of 528, to ground, tripping the brushes 529, 530, 531 into engagement with the bank of trunk terminals leading to the A local incoming switch.

When the 0' counting relay attracts its lower armature a circuit is closed from battery, motor magnet of sequence switch 500, upper right contact of 501, lower armature and front contact of the 0' counting relay, to ground, sending the sequence switch 500 from its eighth and into its tenth position.

The sender sequence switch moving from its eighth onto its tenth position, the 0' counting relay is deenergized allowing its armatures to return to normal, and the office selector switch, being in the third position, a circuit is closed for relay 511 over the circuit heretofore traced. As the relay 511 is energized it closes at its left armature and front contact a circuit from battery, motor magnet of sequence switch 519, upper left contact of 520, left armature and front contact of 511, to ground, to move the sequence switch 519 from its third into its fourth position. The up-magnet 524 is also energized in this position from battery, up-magnet 524, lower and upper right contacts of 518, left armature and front contact of 511, to ground. Also a circuit is prepared from battery, relay 511, conductor 512, upper right and lower left contacts of 525, B commutator to ground, to shunt out the stepping relay 503.

The sender sequence switch is at this time in the tenth position, and a circuit is closed from battery, conductor 505, No. 1 counting relay, conductors 522, 457, 458, left armature and front contact of relay 417, conductor 461, lower right contact of 526, conductor 508, lower left contact of 267, conductor 268, front contact and armature of stepping relay 503 to ground. The up-magnet 524 being energized the brush moves over the B commutator taking as many steps as there are pairs of counting relays to be energized.

On the last step the 0' counting relay is energized from battery and ground at upper and lower right contacts of 510. As the 0' counting relay energizes, it breaks the circuit for the relay 511, which deenergizes, and also closes a circuit to move sequence switch 500 from the tenth and into the twelfth position.

The deenergization of relay 511 broke, at 15 the left armature and front contact thereof, the circuit for the up-magnet 524, stopping the upward movement of the brush carriage. When the left armature of relay 511 reaches its back contact a circuit is closed, at upper 15 right contact of 520, to move sequence switch 519 from its fourth into its fifth position.

Coming into its fifth position a circuit is closed from battery, winding of relay 511, conductor 512, upper right and left contacts of 525, to ground, energizing the relay 511 and closing a circuit to move sequence switch 519 from its fifth and into its sixth position, in which position a circuit is closed from battery, winding of up-magnet 524, 25 lower and upper right contacts of 518, left armature and front contact of 511, to ground, to move the brush carriage upwardly. The relay 511 will be maintained energized in this position through a circuit 30 from battery, winding of relay 511, right armature and front contact thereof, upper right and left contacts of 535, conductor 536, brush 531, terminal 534, to ground, as long as the brush 531 passes over busy trunks. 35 Also a circuit is maintained for the relay 511 to ground at the C commutator while the brush 531 is passing from one terminal 534 to the next. When the terminals 532, 533, 534 of an idle trunk are reached by the 40 brushes 529, 530 and 531, respectively, relay 511 deenergizes, and when its left armature reaches its back contact a circuit is closed to move the sequence switch 519 from its sixth into its eighth position.

45 The sequence switch 519 coming into its eighth position and the brushes 529, 530 and 531 being in contact with the terminals 532, 533, 534, respectively, of an idle trunk, a circuit is closed from battery, relay 600, 50 lower left and upper right contacts of 601, conductor 602, terminal 532, brush 529, conductor 537, upper right and lower left contacts of 513, conductor 514, terminal 278, brush 275, upper left and right contacts of 526, conductor 264, back contact and upper armature of 0' counting relay, stepping relay 503, upper right contact of 504, conductor 265, upper and lower right contacts of 266, brush 276, terminal 279, conductor 60 515, upper and lower right contacts of 516, brush 530, terminal 533, conductor 603, upper right and left contacts of 604, to ground. The relay 600 energizes attracting its armatures and closes a circuit at its left armature 65 and front contact from battery, release con-

trol relay 605, conductor 606, lower right and upper left contacts of 607, left armature and front contact of 600, to ground. It also, at its right armature and front contact, closes an alternate circuit for itself from battery, 70 winding, conductors 608 and 609, upper left and right contacts of 601, over the circuit above traced, keeping the relay 600 energized irrespective of what happens at the lower left contact of 601. The release control relay 605 when energized attracts its armatures, closing at its lower armature and front contact a circuit from battery, motor magnet of sequence switch 610, lower and upper left contacts of 611, conductor 612, 80 front contact and lower armature of 605, to ground, moving the sequence switch from the first into the second position.

The stepping relay 503 is energized over the circuit above traced, attracting its armature and completing a circuit from battery, conductor 505, No. 2 counting relay, armature and back contact of the No. 2' counting relay, conductor 523, conductor 462, upper left contact of 455, conductor 456, lower left contact 90 of 526, conductor 508, lower left contact of 267, conductor 268, armature and front contact of stepping relay 503, to ground.

In the second position of sequence switch 610, with the relay 600 energized, a circuit 95 is closed from battery, winding of up-magnet 613, upper right and left contacts of 607, left armature and front contact of 600, to ground, energizing said up-magnet 613 and moving the brush over the A commutator. As the brush moves over the segments of the A commutator the stepping relay 503 is intermittently shunted out by a circuit extending from ground, A commutator, lower right and upper left contacts of 622, conductor 609, to the circuit through stepping relay 503, causing the successive operation of the pairs of counting relays until the 0' counting relay is energized to break the circuit for the stepping 110 relay 503, and also the relay 600.

The 0' counting relay being energized closes a circuit to move sequence switch 500 from the twelfth into the fourteenth position. The brush moving off the segment of 115 the A commutator, relay 600 deenergizes, closing a circuit at its left armature and back contact to move sequence switch 610 from the second into the third position, and at its left armature and front contact breaking the circuit for the up-magnet 613, stopping the upward movement of the brush carriage. On coming into its third position sequence switch 610 closes a circuit from battery, trip magnet 614, lower left contact 120 of 615, upper left contact of 604, to ground, energizing the trip magnet, and tripping the proper set of brushes into engagement with the terminals of the bank containing the trunk leading to A' final switch. 130

As the sequence switch 500 moves from the twelfth into the fourteenth position the circuit for the relay 600 and stepping relay 503 is again closed in the manner described above.

Relay 600 in energizing closes, as before, an auxiliary circuit through the right armature and front contact thereof to the upper left contact of 601, maintaining the relay 10 energized after sequence switch 610 moves from the third into the fourth position, which occurs when relay 600 attracts its left armature.

With the sequence switch 610 in the fourth position, and the relay 600 energized over the substitute circuit traced through the right armature and front contact, circuit is closed for the up-magnet 613 from battery, winding of magnet 613, upper right 20 and left contacts of 607, left armature and front contact of 600 to ground, moving the brush over the group commutator B.

With the sequence switch 500 in the fourteenth position, and the stepping relay 503 energized, a circuit is closed from conductor 505, the 0' counting relay, conductors 506, 463, 464, upper right contact of 465, lower left contact of 466, conductor 467, upper right contact of 526, conductor 508, lower right contact 267, conductor 268, armature and front contact of stepping relay 503, to ground.

The brush moves over the segments of commutator B, one step for each pair of counting relays, the energization and de-energization of each pair in succession being determined by the energization and de-energization of the stepping relay 503. On the last deenergization of stepping relay 40 503 and the consequent energization of the 0' counting relay, the sequence switch 500 is moved from the fourteenth into the sixteenth position. The relay 600 is deenergized causing the deenergization, at the armature and front contact thereof, of the up-magnet 613 with the brushes 616, 617, 618 in contact with the terminals 619, 620 and 55 621 of the lowermost trunk of the group leading to the A local incoming switch. When the armatures of 600 have been fully retracted, a circuit is closed from battery, motor magnet of sequence switch 610, lower left contact of 611, lower right contact of 699, left armature and back contact of 600, moving the sequence switch 610 from its fourth and into its fifth position.

In the fifth position a circuit is closed from battery, winding of relay 600, upper right contact of 615, upper left contact of 604 to ground, energizing relay 600 and closing, at the left armature and front contact thereof, a circuit to move sequence switch 610 from the fifth into the sixth position.

Also, in the fifth position of sequence

switch 610, a circuit is closed from battery, relay 600, right armature and front contact thereof, conductors 608 and 609, upper and lower left contacts of 622, conductor 623, brush 618, terminal 621 of a trunk terminating at the A final switch, to ground, should such trunk be busy.

In the sixth position of sequence switch 610 a circuit is closed from battery, winding of relay 600, armature and front contact thereof, conductors 608, 609, upper left and lower right contacts of 622, C commutator and to ground at a busy segment thereof. The relay 600 energizing, closes a circuit from battery, up-magnet 613, upper right and left contacts of 607, left armature and front contact of 600, to ground. The brushes 616, 617 and 618 move over the busy terminals 619, 620 and 621 respectively until an idle trunk is found, and the brush 85 moving off the segment of the C commutator, relay 600 is deenergized, breaking the circuit for the up-magnet 613 and stopping the brushes 616, 617 and 618 on the terminals 619, 620 and 621, respectively, of an 90 idle trunk.

The relay 600 deenergizing, a circuit is closed from battery, motor magnet of sequence switch magnet 610, lower left contact of 611, lower right contact of 699, left armature and back contact of 600, to ground, moving the sequence switch from the sixth into the seventh position.

When the sequence switch 610 moves into its seventh position a circuit is closed from 100 battery, relay 600, lower left and upper right contacts of 601, conductor 602, brush 529, conductor 537, upper right and lower left contacts of 513, conductor 514, terminal 278, brush 275, upper left and right contacts of 105 263, conductor 264, upper armature and back contact of the 0' counting relay, stepping relay 503, upper right and left contacts of 504, conductor 265, upper and lower right contacts of 266, brush 276, terminal 279, conductor 515, upper and lower right contacts of 516, brush 530, terminal 533, conductor 603, upper right and left contacts of 604, to ground, energizing the relay 600 and stepping relay 503 in series, and closing a circuit from battery, motor magnet of sequence switch 610, lower left contact of 611, upper right contact of 699, left armature and front contact of relay 600, to ground, moving the sequence switch 610 from its seventh into its 120 eighth position.

When relay 600 energizes, a supplementary circuit through its right armature and front contact, conductor 608, upper left contact of 601, and over the circuit above traced, 125 keeps relay 600 energized through the eighth position of sequence switch 610.

In the eighth position of sequence switch 610, a circuit is closed from battery, relay 538, lower and upper right contacts of 539, 130

conductor 540, terminal 619, brush 616, upper and lower left contacts of 624, conductor 625, left armature and front contact of relay 600, to ground, energizing said relay 538, 5 which attracts its armatures, and at its right armature closing a circuit from battery, release control relay 555, upper left and right contacts of 556, right armature and front contact of relay 538, to ground. Release control relay 555 energizes, closing a circuit from battery, motor magnet of sequence switch 541, lower right contact of 542, left armature and front contact of relay 555, to ground, moving the sequence switch 10 541 out of its first and into its second position. In moving from the first into the second position, sequence switch 541 breaks, at the lower right contact of 539, the energizing circuit for relay 538, but relay 538 15 is maintained energized at its left armature and front contact, lower left contact of 539, over the circuit above traced.

Also, release control relay 555 is maintained energized, after sequence switch 25 leaves its first position, over circuit from battery, winding of relay 555, right armature and front contact thereof, conductor 558, terminal 621, brush 618, conductor 623, lower and upper left contacts of 604, to 30 ground.

With the relay 538 energized and the sequence switch 541 in the second position, a circuit is closed from battery, up-magnet 545, upper and lower left contacts of 556, 35 right armature and front contact of 538, to ground, to move the brush over the A commutator.

In the second position of sequence switch 541, a circuit is provided, to shunt out the 40 stepping relay 503, when the brush engages with the segments of the A commutator, which circuit extends from the intersection of conductors 608 and 609, conductor 626, lower right and upper left contacts of 627, 45 brush 617, terminal 620, conductor 563, upper right contact of 544, upper left contact of 543, the A commutator, to ground.

Relay 503 being energized and sequence switch 500 being in the sixteenth position, 50 a circuit is closed from battery, conductor 505, No. 3 counting relay, conductors 559, 560, upper right contact of 561, conductor 562, upper left contact of 526, conductor 508, lower left contact of 267, conductor 268, 55 armature and front contact of stepping relay 503, to ground. As the brush comes into engagement with segments of the A commutator the stepping relay 503 will be intermittently shunted out, the brush taking 60 one step for each energization and deenergization of the stepping relay, and will take as many steps as there are pairs of counting relays from 3 and 3' down to and including the 0 and 0' counting relays. As the 0' 65 counting relay is energized it breaks perma-

nently the circuit through the stepping relay 503, preventing further stepping of the brush over the segments of commutator A and moving the sequence switch 500 from the sixteenth into the second position. 70

Ground having been removed from the energizing circuit of 600, at the upper armature and back contact of the 0' counting relay, and the brush having passed off the A commutator segments relay 600 deenergizes, 75 deenergizing in turn the relay 538 which breaks the circuit of the up-magnet 545, stopping the upward movement of the brush, and closes a circuit at the right armature and back contact of the relay 538 to move 80 the sequence switch 541 from its second into its third position, closing a circuit from battery, trip magnet 554, lower right and upper left contacts of 553, tripping the brushes 546, 547, 548 into engagement with 85 the bank of terminals leading to the calling subscriber's line. The relay 600 when it deenergizes closes a circuit at its left-hand armature and back contact, moving the sequence switch 610 from the eighth into the 90 ninth position.

The sequence switch 500 having moved from the sixteenth into the second position, the energizing circuit for the 0' counting relay is broken, and its upper armature retracting, a circuit is closed for the relay 600 95 as hereinbefore traced above.

In passing through positions seventeen and eighteen sequence switch 500 closes a circuit from battery, motor magnet of sequence switch 226, conductor 227, upper right contact of 281, conductor 282, upper left contact of 510, to ground, moving sequence switch 226 from the tenth and into 100 the eleventh position. 105

The relay 600 energizing, closes, at its left armature and front contact, a circuit for the sequence switch 610, moving the same from the ninth into the tenth position.

In the tenth position of the sequence 110 switch 610 with the relay 600 energized as above described, a circuit is closed from battery, winding of relay 538, upper and lower right contacts of 539, conductor 540, terminal 619, brush 616, upper and lower left 115 contacts of 624, conductor 625, left armature and front contact of relay 600, to ground. The relay 538 energizing closes a locking circuit for itself at its left armature and front contact and the lower left contact of 120 529, over the circuit just traced, and at its right armature and front contact closes a circuit for the sequence switch 541, moving the same from the third into the fourth position, where a circuit is closed from battery, winding of up-magnet 545, upper and lower left contacts of 556, right armature and front contact of 538, to ground. 125

In this position of sequence switch 541 with the up-magnet 545 energized, the brush 130

is in position to move over the segments of the B commutator. Relay 600 and stepping relay 503 are energized in series, and a shunt for the energizing circuit thereof extends 5 over the conductor 563, as above described, but finds ground at the B commutator. Also, a circuit is closed from battery, conductor 505, No. 4 counting relay, armature and back contact of No. 4' counting relay, 10 conductors 564, 565, lower left contact of 566, conductor 567, lower right contact of 568, conductor 569, lower right contact of 267, conductor 268, armature and front contact of stepping relay 503, to ground, energizing said No. 4 counting relay. As the brush moves over the segments of the B commutator, the stepping relay 503 is intermittently shunted out, causing the successive energization of the pairs of counting 15 relays, 4, 4', 3, 3', 2, 2', 1, 1', 0, 0', so that the brush will move four steps or until the 0' counting relay is energized, at which time the circuit through the stepping relay 503 and relay 600 will be broken at the upper armature and back contact of said 0' counting relay, and a circuit for the sequence switch 500 closed at the lower armature and front contact of said 0' counting relay, moving the sequence switch 503 from the second 20 and into the fourth position.

Relay 600 is deenergized breaking at its left armature and front contact a circuit for the relay 538 which deenergizes and at its right armature and back contact closes a 25 circuit for the sequence switch 541, moving the same from the fourth into the fifth position. At the same time a circuit is closed at the left armature and back contact of the relay 600 to move the sequence switch 610 from its tenth into its eleventh position. The circuit for the up-magnet 545 is also broken at the right armature and front contact of relay 538, stopping the upward movement 30 of the brush carriage.

In the eleventh position of sequence switch 610, a circuit is again established for the relay 600 at the lower left contact of 601 and the circuit above traced through the stepping relay 503, causing the energization 35 of said relay 600, and at its left armature and front contact closing a circuit, moving the sequence switch 610 from the eleventh into the twelfth position, and also at the same point and at the lower and upper right contacts of 539 closing an energizing circuit 40 for the relay 538. The relay 538 energizing closes at its right armature and front contact a circuit, moving the sequence switch 541 from its fifth into its sixth position.

A locking circuit for the relay 538 in the 45 sixth position of the sequence switch 541 is maintained from battery, through the winding of said relay 538, left-hand armature and front contact thereof, lower left and upper right contacts of 538, over the circuit above

traced, through the left armature and front contact of the relay 600. The up-magnet 545 is energized from battery, winding of said magnet 545, lower and upper left contacts of 556, right armature and front contact of relay 538, to ground. 50

The relay 600 being energized over the circuit which includes the stepping relay 503, and the sequence switch 500 being in its fourth position, a circuit is closed from battery, conductor 505, No. 2 counting relay, armature and back contact of the No. 2' counting relay, conductors 523, 570, upper right contact of 571, conductor 572, upper right contact of 568, conductor 569, lower left contact of 267, conductor 268, armature and front contact of stepping relay 503, to ground. The brush moving over the segments of commutator C alternately deenergizes and energizes the stepping relay 503, 55 and operates the pairs of counting relays 2, 2', 1, 1', 0, 0' in succession until the 0' counting relay is energized, when the circuit through the stepping relay 503 is permanently broken. The sequence switch 500, 60 upon the energization of the 0' counting relay, moves from its fourth into its eighth position.

The relay 600 being deenergized the circuit for the relay 538 is broken at its left armature and front contact. When the left armature of relay 600 reaches its back contact a circuit is closed for the sequence switch 610, moving the same from the twelfth into the thirteenth position. 65

Relay 538 deenergizing, breaks at its right armature and front contact the circuit for the up-magnet 545 and closes at its right armature and back contact a circuit for the sequence switch 541, moving the same from the sixth into the seventh position. 70

As the sequence switch 500 passes through the fifth and sixth positions a circuit is closed from battery, sequence switch 226, conductor 227, lower right contact of 281, 75 conductor 283, lower left contact of 510 to ground, moving sequence switch 226 from the eleventh into the twelfth position.

As the sequence switch 226 moves into its twelfth position a circuit is closed for relay 80 600 from battery, winding of said relay 600, lower left and upper right contacts of 601, conductor 602, terminal 532, brush 529, conductor 537, upper right and lower left contacts of 513, conductor 514, terminal 278, 85 conductor 275, upper left and lower right contacts of 263, conductor 284, lower left contact of 274 to ground. The relay 600 energizing closes at its left armature and front contact a circuit to send the sequence switch 90 610 from the thirteenth into the fourteenth position.

The test relay 285 is energized from the second to the twelfth position of the sequence switch 226 over the circuit; battery, 95

- impedance 286, lower right and upper left contacts 231, conductor 198, terminal 193, brush 189, conductor 97, terminal 122, brush 108, conductors 96, 103, substation set of 6 the calling subscriber, conductors 104, 95, brush 109, terminal 123, conductor 94, brush 190, terminal 194, conductor 199, lower left and upper right contacts of 232, winding of test relay 285, impedance 287, to ground.
- 10 If for any reason the calling line is not seized, the relay 285 will not have its winding shunted out and will therefore remain deenergized, holding the sequence switch 226 in its twelfth position. In the twelfth position of this sequence switch, a circuit is completed from grounded battery through a lamp 900, upper right and lower left contacts of 901, to ground through an interrupter 902. This lamp will continue to flash 15 and inform the operator that the calling line has not been seized, and that the sequence switch 226 has not moved out of position 12.

When the brushes 546, 547, 548 are 25 brought into engagement with the terminals 549, 550 and 551, respectively, of the calling line, a ground is placed on the winding of the test relay 285 from conductor 95, by way of conductor 572, terminal 549, brush 546, 30 upper right and left contacts of 539, conductor 540, terminal 619, brush 616, upper right and left contacts of 624, conductor 603, terminal 533, brush 530, upper and lower right contacts of 516, conductor 515, terminal 279, brush 276, upper right and left contacts of 266, through the impedance 287 to ground, deenergizing the test relay 285, which at its right armature and back contact closes a circuit to move sequence switch 226 from 35 the twelfth into the thirteenth and through the thirteenth into the fourteenth position.

It will be remembered that the relay 101 was locked up over circuit: battery, right winding of relay 117, left armature and 40 front contact thereof, conductor 116, contact 107, upper winding of 101 to ground. Now when the test relay 285 is deenergized, as above described, a ground is placed on the locking circuit of relay 101 from conductors 45 116, 197, brush 188, terminal 192 of the line switch shown in Fig. 2, conductor 196, upper left and right contacts of 288, left armature and back contact of the test relay 285, right armature and back contact of 224 to ground.

55 The relay 101 deenergizing allows its armatures to retract, deenergizing the relay 118 and breaking the connection from substation 4342 to the recording device shown in Fig. 5. Also the line switch brushes 106, 107, 108 and 109 are removed from engagement with the terminals 120, 121, 122, 123, respectively, disconnecting the line switch shown in Fig. 1 from the line switch shown in Fig. 2. When sequence switch 226 leaves 60 position 13, the circuit which shunted out re-

lay 101 and maintained the locking circuit of relay 117 is broken at the upper contacts of 288, and relay 117 deenergizes, and when its left armature retracts, breaks the locking circuit for the relay 114, allowing said 70 relay to return to normal, breaking the engagement existing between brushes 187, 188, 189, 190 and terminals 191, 192, 193, 194, respectively, of the line switch shown in Fig. 2.

75 The relay 600, which was energized when sequence switch 226 passed into the twelfth position, is deenergized when sequence switch moves out of the twelfth and into the thirteenth position, by the breaking of 80 lower right contact of 263. On deenergizing it closes at its left armature and back contact a circuit for the sequence switch 610, moving said sequence switch from the fourteenth into the fifteenth position.

85 The sequence switch 610 passing into the fifteenth position a circuit is closed for relay 628 from battery, upper and lower left contacts of 629, conductor 648, lower right and left contacts of 651, conductor 602, terminal 532, brush 529, conductor 537, upper right and lower left contacts of 513, conductor 514, terminal 278, brush 275, upper left and right contacts of 263, conductor 264, upper armature and back contact of the 0' counting relay, stepping relay 503, upper right and left contacts of 504, conductor 265, upper and lower right contacts of 266, brush 276, terminal 279, conductor 515, upper and lower right contacts of 516, brush 530, terminal 533, conductor 603, upper and lower right contacts of 652, conductor 649, upper left and lower right contacts of 630, to ground.

90 Relay 628 energizing closes at its left 105 armature and front contact a circuit from battery, release control relay 631, lower left and upper right contacts of 632, left armature and front contact of 628 to ground, energizing the release control relay, which 110 at its right armature and front contact closes a circuit from battery, sequence switch 633, lower left contact of 634, right armature and front contact of 631 to ground, moving the sequence switch from its first and into its 115 second position.

95 After the sequence switch 633 leaves its first position, the release control relay 631 is held energized over circuit: battery, winding of said relay, left armature and front 120 contact thereof, conductor 650, upper right and lower left contacts of 695 to ground. In addition to the energizing circuit for the relay 628 traced above, in the second positions of sequence switch 633 a second possible energizing circuit is closed for said relay from battery, winding of said relay, right armature and front contact thereof, conductor 654, lower right and left contacts of 635, the "A" commutator and to ground, 130

when the brush is in engagement with any segment of said commutator. Also in the second position of the sequence switch 633 a circuit is closed from battery, up magnet 636, upper left and right contacts of 632, left armature and front contact of 628, to ground.

5 The energization of the up-magnet 636 causes the brush to move over the segments 10 of the "A" commutator. The relay 628 being energized over the circuit as traced above and this energizing circuit also being the energizing circuit for the stepping relay 503, said stepping relay is energized, 15 and at its armature and front contact closes a circuit to ground from battery, the No. 2 counting relay, armature and back contact of No. 2' counting relay, conductor 523, conductor 459', upper armature and front 20 contact of relay 422, conductor 460', upper left contact of 568, conductor 569, lower right contact of 267, conductor 268, armature and front contact of stepping relay 503 to ground.

25 The No. 2 counting relay is energized over the circuit just traced, attracting its armature and preparing a circuit for the No. 2' counting relay. In the meantime the brush is moving over the "A" commutator segments, and in coming into engagement with the first segment, ground will be found thereon which will shunt out the stepping relay 503, deenergizing the same, and as has been heretofore described, removing the 30 ground from conductor 523, allowing the No. 2' counting relay to be energized from battery and to ground at lower right contact of 510. The brush moving off the segment, the original circuit through the 35 relay 628 and stepping relay 503 is again established energizing the stepping relay 503, and a second time placing ground from battery on the conductor 523, this time, however, through the No. 1 counting relay and 40 upper armature and front contact of the No. 2' counting relay.

The brush will continue to move over the commutator segments until it has taken as many steps as there are pairs of counting 45 relays Nos. 2, 2', 1, 1', 0, 0' or three steps. When the 0' counting relay has been reached and the stepping relay 503 deenergized, the circuit for said stepping relay will be permanently broken at the upper 50 armature and back contact of the 0' counting relay. The brush not being at this time in contact with a segment of commutator "A," the circuit for relay 628 is broken, allowing the armatures thereof to be retracted, 55 and a circuit is established at the left armature and back contact thereof and upper right contact of 634, moving the sequence switch 633 from the second into the third position, and the circuit of the up-magnet 636 is broken at the left armature and front

contact of said relay 628. In the third position a circuit is closed from battery, trip magnet 655, lower and upper contacts of 646, to ground, energizing said trip magnet, tripping the proper set of brushes 637, 638, 639 into engagement with the proper bank of terminals.

When the 0' counting relay was energized it closed a circuit at its lower armature and front contact for the sequence 75 switch 500, moving the same from the eighth into the tenth position.

The sequence switch 633 coming into its third position, a circuit is closed for the relay 628 at the lower and upper left contacts 80 of 629 over the circuit heretofore traced for said relay. When the relay 628 is energized it establishes, at its left armature and front contact and through the upper left contact of 634, a circuit to move the sequence switch 85 633 from its third into its fourth position, and also at its armature and front contact a circuit for the up-magnet 636 through the upper left and right contacts of 632. The energizing circuit that existed for the relay 90 628 in the third position of sequence switch 633, is broken at the lower left contact of 629; when the sequence switch 633 leaves its third position, but a circuit is maintained for this relay, after leaving the third position and while in the fourth position, from right armature and front contact of said relay 628, and lower right and upper left contacts of 629, over the original energizing circuit above traced.

Further, a supplementary circuit exists for this relay 628 from battery, winding thereof, right armature and front contact, lower and upper left contacts of 635, the "B" commutator to ground, the last named 105 circuit being completed whenever the brush moves onto a segment of the "B" commutator. At this instant, the relay 628 and stepping relay 503 being energized over the circuit as traced, a circuit is completed from battery, conductor 505, the No. 1 counting relay, armature and back contact of the No. 1' counting relay, conductor 522, upper armature and front contact of relay 426, upper armature and front contact of relay 419, 110 lower right contact of 575, conductor 569, lower right contact of 267, conductor 268, armature and front contact of stepping relay 503 to ground.

The up-magnet 636 being energized, the 120 brush moves over the "B" commutator. As before when the brush contacts with a segment of the "B" commutator, the ground on said segment is substituted for the ground of the original energizing circuit 125 for relay 628, deenergizing stepping relay 503, which allows its armatures to retract, removing ground from conductor 522 and allowing the 1' counting relay to be energized. The brush moving off such segment, 130

the original ground for the energizing circuit of relay 503 is restored, and it again energizes. The brush will move as many steps as there are pairs of counting relays 5 to be engaged, or in this case two steps, until the 0' counting relay again comes into action, destroying the energizing circuit for relay 628 and stepping relay 503, the brush set 637, 638, 639 being stopped in engagement with the terminals of the lowermost trunk in the third group of trunks.

The 0' counting relay being energized moves sequence switch 500 from its tenth and into its twelfth position. The relay 628 15 being deenergized at its left armature and back contact, closes a circuit for sequence switch 633, moving the same into the fifth position, and at the same armature and front contact breaking the circuit for the 20 up-magnet 636.

In the fifth position a circuit is again established for relay 628 from battery, through the winding of said relay, lower left and upper right contacts of 629 to 25 ground, and when said relay attracts its armatures, it closes at its left armature and front contact and upper left contact of 634 a circuit to move the sequence switch 633 out of the fifth and into the sixth position. Also 30 this relay 628 at its right armature and front contact establishes an alternate circuit for itself through lower left and right contacts of 635, the "C" commutator to ground.

In the sixth position of sequence switch 35 633 a circuit is again established for the up-magnet 636 from battery, upper left and right contacts of 632, left armature and front contact of 628 to ground. The brush carriage will be moved upwardly until the 40 brushes 637, 638 and 639 come into engagement with the terminals 640, 641 and 642, respectively, of an idle trunk, when relay 628 will be deenergized, closing, at its left armature and back contact and upper right 45 contact of 634, a circuit to move the sequence switch 633 out of the sixth through the seventh and into the eighth position.

The up-magnet 636 is, of course, immediately deenergized due to the breaking of its 50 circuit at the left armature and front contact of relay 628.

In position 8 of the sequence switch 633 a circuit is again established for relay 628 through the stepping relay 503 as heretofore 55 traced, but this time going to ground at the upper left and lower right contacts of 630. The relay 628 is again energized, and at its left armature and front contact closes a circuit to move the sequence switch 633 from its 60 eighth into its ninth position.

In the ninth position of sequence switch 633 a circuit is closed for relay 656 from battery, winding of said relay 656, lower right and upper left contacts of 657, conductor 682, terminal 642, brush 639, lower 65

right and left contacts of 643, left armature and front contact of 628 to ground. The relay 656 energizing closes at its right armature and front contact a circuit from battery, release control relay 658, lower left and 70 right contacts of 661, right armature and front contact of 656 to ground, energizing said release control relay 658, which at its right armature and front contact closes a circuit from battery, motor magnet of sequence switch 660, lower left contact of 761, right armature and front contact of release control relay 658 to ground, moving the sequence switch 660 from its first into its second position. 80

In the second position of sequence switch 660 a circuit is closed from battery, up-magnet 662, upper and lower right contacts of 661, right armature and front contact of 656 to ground. The relay 628 is energized 85 at this time and a substitute circuit therefor may be established from battery, winding of said relay, right armature and front contact thereof, lower left and upper right contacts of 644, brush 638, terminal 641, conductor 683, upper left and lower right contacts of 663, a segment of "A" commutator to ground. 90

The relay 628 being energized the stepping relay 503 is likewise energized, attracting its 95 armature and closing a circuit from battery, conductor 505, No. 1 counting relay, armature and back contact of the No. 1' counting relay, conductor 522, conductor 468, upper armature and front contact of relay 429, 100 conductor 469, lower left contact of 575, conductor 569, lower right contact of 267, conductor 268, armature and front contact of stepping relay 503 to ground.

The up-magnet 662 being energized the 105 brush starts to move over the "A" commutator segments, shunting out the stepping relay 503 until the 0' counting relay is energized, when the energizing circuit for the stepping relay 503 and relay 628 is broken 110 at the upper armature of the 0' counting relay.

The 0' counting relay energizing allows sequence switch 500 to move from its twelfth into its fourteenth position. 115

Relay 628 deenergizing breaks at its left armature and front contact the circuit for relay 656, which relay is deenergized closing at its right armature and back contact a circuit to move the sequence switch 660 from 120 its second into its third position, and breaking at its right armature and front contact the circuit for the up-magnet 662. Relay 628 deenergizing closes at its left armature and back contact a circuit to move sequence switch 633 from its ninth into its tenth position. 125

Sequence switch 500 being in the fourteenth position, a circuit is closed from battery, winding of relay 628, upper and lower 130

left contacts of 629, through the circuit traced above for said relay 628 and stepping relay 503, upper left and lower right contacts of 630 to ground.

- 5 Relay 628 being energized as above described, it closes at its left armature and front contact a circuit moving the sequence switch 633 from its tenth into its eleventh position, and at the same time at its right armature and front contact closes a substitute circuit to lower right and upper left contacts of 629 to ground, over the original energizing circuit traced above.
- 10 On coming into the eleventh position, a circuit is closed from battery, winding of relay 656, lower right and upper left contacts of 657, conductor 682, terminal 642, brush 639, lower right and left contacts of 648, left armature and front contact of 628 20 to ground.

The relay 656 being energized, closes at its right armature and front contact a circuit for sequence switch 660, moving the same from its third into its fourth position.

- 25 The sequence switch 500 being, at this time in its fourteenth position and the stepping relay 503 being energized over the circuit above traced for relay 628, a circuit is closed from battery, conductor 505, No. 8 30 counting relay, armature and back contact of No. 8' counting relay, conductor 576, conductor 471, upper armature and front contact of relay 432, conductor 472, upper right contact of 575, conductor 569, lower right contact of 267, conductor 268, armature and front contact of stepping relay 503 to ground.

The relay 656 being energized and the sequence switch 660 being in the fourth position, a circuit is closed for the up-magnet 662 at the right armature and front contact of said relay 656. Also a ground from a segment of the "B" commutator may be placed on the energizing circuit of the relay 45 628 and stepping relay 503.

- As has been heretofore described the brush will contact with as many segments of the "B" commutator as there are pairs of counting relays energized in succession—in this 50 case nine steps. The stepping relay 503 will, therefore, be energized and deenergized nine times or until the 0' counting relay is energized, at which time the brushes 669, 670, 671, are in engagement with the ninth 55 set of 10's terminals in the bank of terminals, and the circuit for both the relay 628 and stepping relay 503 broken at the upper armature and back contact of said 0' counting relay, which at its lower armature and front 60 contact closes a circuit to move the sequence switch 500 from its fourteenth and into its sixteenth position.

The relay 628 being deenergized breaks at its left armature and front contact a circuit 65 for the relay 656 which in turn deenergizes,

breaking at its right armature and front contact the circuit for the up-magnet 662, stopping the upward movement of the brush carriage, and at the right armature and back contact closing a circuit to move the sequence switch 660 from its fourth into its fifth position. The relay 628 upon its deenergization also closes a circuit for the sequence switch 633, moving the same from its eleventh into its twelfth position.

The sequence switch 500 having moved from its fourteenth into its sixteenth position, the 0' counting relay is deenergized and closes at its upper armature and back contact a break point in the energizing circuit for the relay 628 and stepping relay 503, and on the sequence switch 633 coming into its twelfth position the energizing circuit for the relay 628 and stepping relay 503 is again established, and the relay 628 attracting its 80 armatures closes at its left armature and front contact a circuit to move the sequence switch 633 from its twelfth into its thirteenth position.

A substitute circuit is likewise established 90 at the right armature and front contact of said relay 628 through the lower right and upper left contacts of 629, which circuit is maintained in the thirteenth position of sequence switch 633. In this position of the 95 sequence switch a circuit for the relay 656 is again established at the left armature and front contact of relay 628, energizing said relay 656 and at its right armature and front contact closing a circuit to move the sequence 100 switch 660 from the fifth into the sixth position, and at said right armature and front contact closing in the sixth position of the sequence switch 660 a circuit for the up-magnet 662.

The relay 628 and stepping relay 503 being energized, a circuit is closed from battery, conductor 505, the No. 2 counting relay, armature and back contact of the No. 2' counting delay, conductor 523, lower armature and front contact of relay 436, conductor 473, upper left contact of 575, conductor 569, lower right contact of 267, conductor 268, armature and front contact of stepping relay 503 to ground.

The brush is now moved up over the "C" commutator due to the energization of the up-magnet 662, and in passing over the segments shunts out, as hereinbefore described, the stepping relay 503 so that the brush will 120 take as many steps as there are pairs of counting relays to be energized—in this case three pairs.

The brushes 669, 670 and 671 on coming into engagement with the terminals 672, 673 and 674, respectively, of the called line, the circuit through the relay 628 is broken, deenergizing this relay, and at its left armature and back contact closes a circuit for the sequence switch 633, moving this sequence 130

switch from the thirteenth into the sixteenth position. The relay 628 also at its left armature and front contact breaks the energizing circuit for the relay 656, which relay 5 energizes, and at its right armature and back contact closes the circuit for the sequence switch 660, moving the same from its sixth into its seventh position.

As sequence switch 610 comes into its fifteenth position a circuit is closed from battery, one winding of the repeating coil 653, supervisory relay 685, upper right and left contacts of 627, brush 617, terminal 620, conductor 563, upper right and left contacts 10 of 544, brush 547, terminal 550, conductor 573, conductor 103, the calling subscriber's apparatus, conductor 104, conductor 572, terminal 549, brush 546, upper left and right contacts of 539, conductor 540, 15 terminal 619, brush 616, upper left and lower right contacts of 624, to battery. 20

When sequence switch 226 leaves position 16, the locking circuit of release-control relay 517 is broken at the upper right and lower left contacts of 274. Relay 517 deenergizes and completes a circuit at its right armature and back contact to move the sequence switch 519 out of position 8 and into position 17. This circuit extends 25 from grounded battery, winding of motor magnet of sequence switch 519, lower right contact of 520, armature and back contact 30 of relay 517 to ground.

As soon as sequence switch 519 leaves position 9, the locking circuit of release-control relay 605 is broken at the upper left contact of 535. Relay 605 deenergizes and completes a circuit from grounded battery, winding of motor magnet of sequence switch 40 610, lower left and upper right contacts of 611, lower armature and back contact relay 605 to ground, for moving sequence switch 610 from position 15 to position 16.

When sequence switch 519 arrives in position 17, a circuit is completed from grounded battery, winding of down-drive magnet 580, lower right and left contacts of 528 to ground. The brushes 529, 530 and 531 are restored to their normal position, 45 and when they reach their lowermost position, a circuit will be completed from grounded battery, winding of motor magnet of sequence switch 519, upper right contact of 581 to ground, through the Y 50 commutator segment to ground, for moving sequence switch 519 out of position 17 into position 1.

In the sixteenth position of sequence switch 610 a circuit is closed from battery, 55 winding of relay 656, lower right and upper left contacts of 657, conductor 682, terminal 642, brush 639, lower right and upper left contacts of 643, conductor 648, lower and upper right contacts of 651 to ground, energizing said relay, and at its right armature

and front contact closing a circuit to move sequence switch 660 from its seventh into its eighth position.

On passing out of its seventh position the sequence switch 660 breaks the energizing circuit for relay 656 at the lower right contact of 657. If the line on the terminals of which the brushes are now in contact is idle, a circuit will be closed through upper left and lower right contacts of 664, relay 665, 70 lower right and upper left contacts of 666, through the upper winding of said relay 665 to ground. This relay attracting its armatures will be held locked up at the lower right contact of 664 from the eighth into 75 the fourteenth position of sequence switch 660. The energization of relay 665 has also at the upper armature and front contact and upper right contact of 696 closed a circuit to move sequence switch 660 from the eighth into the tenth position. The relay 656 being deenergized at this time, closes 80 at its right armature and back contact a circuit to move the sequence switch 660 from its tenth into its twelfth position, 90 where another energizing circuit for said sequence switch will be found closed at upper right contact of 696 and upper armature and front contact of relay 665 to move 95 the sequence switch from its twelfth into its fourteenth position.

The relay 685 is energized attracting its armature, and when sequence switch 610 comes into its sixteenth position a circuit is closed from battery, relay 687, upper 100 right and left contacts of 688, armature and front contact of 685 to ground.

The relay 687 being energized at its right armature and front contact, connects the ringing device 689 to the called subscriber's line over path from ringing device, relay 690, right armature and front contact of relay 687, lower left and upper right contacts of 652, conductor 649, upper left and right contacts of 644, brush 638, terminal 110 641, conductor 683, upper left and right contacts of 680, brush 670, terminal 673, conductor 693, through the called subscriber's signaling device and back over conductor 694, terminal 674, brush 671, upper right and left contacts of 657, conductor 682, terminals 642, brush 639, lower right and upper left contacts of 643, conductor 648, lower and upper right contacts of 651 to ground. 115

In circuit with the ringing device is a relay 690 which will not operate when the substation bells and condenser are included in its circuit, but as soon as the called subscriber removes his receiver from the hook 125 it energizes attracting its armature, closing a circuit from battery, motor magnet of sequence switch 610, lower right contact of 686, armature and front contact of relay 690 to ground, moving said sequence switch 120 130

from its sixteenth into its seventeenth or talking position. The relay 690 will also be energized if the ringing current is diverted to ground through a winding of the busy back device.

- 5 In the seventeenth position of sequence switch 610 a circuit is closed from battery, one winding of repeating coil 653, supervisory relay 691, upper left and right contacts of 652, conductor 649, upper left and right contacts of 644, brush 638, terminal 641, conductor 683, upper left and right contacts of 680, brush 670, terminal 673, conductor 693, out through the subscriber's 10 apparatus, back through conductor 694, terminal 674, brush 671, upper right and left contacts of 657, conductor 682, terminal 642, brush 639, lower right and upper left contacts of 643, conductor 648, lower right and 15 upper left contacts of 651, winding of repeating coil 653, back to battery.

- When the sequence switch 500, due to the energization of the 0' counting relay, passes from the sixteenth into the eighteenth position, a circuit is closed from battery, magnet of sequence switch 226, upper right contact of 281, conductor 282, upper left contacts of 510 to ground, moving said sequence switch from its fourteenth into its 20 fifteenth position, at which point a circuit is closed from battery, motor magnet of sequence switch 500, lower left contact of 577, conductor 578, lower right and left contacts of 271, to ground, moving the sequence 25 switch 500 from the eighteenth into the first or normal position.

- On leaving the fourteenth position the sequence switch 226 breaks at the upper left contact of 257 the holding circuit for the 30 registers.

- On coming into the fifteenth position, circuits will be closed to ground at the upper left contact of sequence switch spring 255 and contacts of sequence switch spring 290 for the sequence switches 402 of the thousands, hundreds, tens, and units registers, for moving said sequence switches from the positions in which they were resting through the eighteenth and into their normal positions.

- 35 In moving out of the fourteenth position, sequence switch 226 also broke the energizing circuit for relay 256 at the upper left contact of 257, destroying the locking circuit for the lock-up register relays of the 40 district office, thousands, hundreds, tens, and units registers, shown in Figs. 8, 9, and 10.

- With relay 256 deenergized, and sequence switch 226 in the fifteenth position, a circuit is closed from battery, motor magnet 45 of sequence switch 226, conductor 227, right contact of 228, armature and back contact of 256, lower left and right contacts of 288, conductor 579, lower left and upper right contacts of 482, of the thousands, hundreds, 50 tens, and units registers of the lines, as call-

ing lines, to ground, moving sequence switch 226 from the fifteenth through the sixteenth and seventeenth, and into the eighteenth position.

In the eighteenth position a circuit is closed from battery, down magnet 290, lower left and right contacts of 273 to ground, returning the brush carriage to the bottom of the terminal bank. When the brush carriage reaches the bottom of the bank of terminals a circuit is closed from battery, motor magnet of sequence switch 226, lower left contact of the "Y" commutator to ground, moving the sequence switch 226 from the eighteenth into its first or normal position.

Conversation is now taking place between the calling and called subscribers, the talking circuit existing as above traced, the only apparatus in use during the connection being that represented in Figs. 15, 18, 19 and 17. All other apparatus used in making the connection has been returned to normal in condition for another call.

Conversation between the subscribers having terminated, we will assume that the calling subscriber is the first to hang up his receiver. The hanging up of the receiver breaks the energizing circuit for the supervisory relay 685, closing a circuit from battery, motor magnet of sequence switch 610, upper left contact of 686, armature and back contact of 685 to ground, moving sequence switch 610 from the seventeenth into the eighteenth position, in which position a circuit is closed from battery, down magnet 698, lower right contact of 615, upper left contact of 604 to ground, energizing the same and causing the return of the brush carriage.

On the brush carriage reaching lowermost position a circuit is closed from battery, motor magnet of sequence switch 610, lower left and right contacts of 611 to ground at the "Y" commutator, moving the sequence switch 610 from its eighteenth into its first or normal position.

On leaving the seventeenth position the sequence switch 610 broke, at the lower left contact of 604, the circuit for the release control relay 555, and when the armatures of said release control relay are retracted a circuit is closed at the left armature and back contact thereof and the lower left contact of 542 to move the sequence switch 541 from its seventh through its ninth and into the tenth position.

The relay 538 being at this time deenergized, a circuit is closed at the right armature and back contact thereof and upper left contact of 542 to move sequence switch 541 from its tenth into its eleventh position, at which time a circuit is again closed at the left armature and back contact of release control relay 555 and lower left contact of 542 to move sequence switch 130

541 from the twelfth through the seventeenth and into the eighteenth position.

In the eighteenth position of sequence switch 541 a circuit is closed from battery, down magnet 552, lower and upper left contacts of 553 to ground. The energization of the down magnet moves the brush carriage back to the bottom of the bank of contacts, and in the lowermost position a circuit is closed at the upper left contact of 557, ground at the "Y" commutator, to move the sequence switch 541 from the eighteenth into the first or normal position.

As the apparatus shown in Fig. 18 passed 15 out of its seventeenth and into the eighteenth position, the talking circuit from the repeating coil 553 to the called subscriber is broken at upper left contacts of 651 and at 652, respectively. Also at the 20 upper right contact of 695 the circuit for the release control relay 631 is broken, allowing said relay to retract its armatures. When its right armature is fully retracted a circuit is closed from battery, magnet of 25 sequence switch 633, lower right contact of 634, right armature and back contact of release control relay 631 to ground, moving the sequence switch 633 from the sixteenth through the seventeenth and into the 30 eighteenth position, where a circuit is closed from battery, down magnet 645, lower right and upper left contacts of 646 to ground.

The brush carriage is moved downward, and when the lowermost position is reached, 35 a circuit is closed at the lower left contact of 647 to ground at the "Y" commutator, moving the sequence switch 633 from its eighteenth and into its first or normal position.

40 When the sequence switch 633 leaves its sixteenth position a circuit is broken for the release control relay 658, which retracts its armatures closing at its right armature and back contact a circuit to move the sequence 45 switch 660 from its fourteenth through its sixteenth and into the seventeenth position.

In the sixteenth position, should the 50 called subscriber still have his receiver off the switchhook, a circuit is closed from battery, relay 656, upper and lower right contacts of 657, brush 671, terminal 674, conductor 694, through the subscriber's apparatus and back over conductor 693, terminal 55 673, brush 670, upper and lower right contacts of 680 to ground.

The apparatus at the "B" final switch 60 will remain in this position until after the hanging up of the receiver by the called subscriber. When he does hang up his receiver the circuit through the relay 656 is broken, allowing its armatures to retract, closing in the seventeenth position of the sequence switch a circuit at right armature and back contact to move said se-

quence switch from its seventeenth into its eighteenth position.

In the eighteenth position a circuit is closed from battery, down magnet 676, upper right and left contacts of 677 to ground, energizing said down magnet and insuring the return of the brush carriage to normal. When the brush carriage reaches its lowermost position a circuit is closed at the lower right contact of 696 to ground at the "Y" commutator, moving the sequence switch 660 from its eighteenth into its first or normal position.

All parts of the apparatus are now in normal position and in condition to receive 30 a call.

In tracing this call we proceeded on the assumption that the party called was idle, and that therefore connection was established immediately between the calling and called subscribers. If, however, the called party is busy connection will not take place between the two subscribers, and after a busy-back signal is sent to the calling subscriber to inform him that the line wanted 35 is busy, the apparatus must be set back to normal, as in the case of a successful call.

The apparatus shown in Fig. 17 comes into the eighth position to test the line on the terminals of which the brushes are in engagement. If the line is busy ground will be found on the terminals thereof and the relay 665 will not be energized. A circuit will therefore be closed in the eighth position of sequence switch 660 from battery, relay 656, lower left and right contacts of 677, armature and back contact of private branch exchange relay 678, upper armature and back contact of relay 665 to ground, moving sequence switch 660 from the eighth 105 into the tenth position.

On coming into the tenth position a circuit is closed from battery, energizing winding of private branch exchange relay 678, lower and upper right contacts of 679 to ground, energizing the private branch exchange relay and breaking the energizing circuit for the relay 656 at its armature and back contact. The right armature of the relay 656 retracting closes a circuit to move 115 sequence switch 660 from the tenth into the twelfth position.

As the sequence switch moves out of the tenth position the circuit for the private branch exchange relay 678 is broken at the lower right contact 679, and as the sequence switch moves into its twelfth position a circuit is closed for down magnet 676 from battery, winding of said down magnet, upper and lower right contacts of 677, armature and back contact of private branch exchange relay 678, upper armature and back contact of relay 665 to ground, energizing the down magnet and sending the brush carriage to the bottom of the bank of terminals. 130

When the brush carriage reaches its lowest position a ground will be found on the "Y" commutator, closing the energizing circuit for sequence switch 660, moving 5 the same from the twelfth through the fourteenth and into the fifteenth position, at which position a busy tone will be sent to the calling subscriber from the busy tone apparatus connected to the line at upper and 10 lower left contacts of 660.

The calling subscriber then, as in the case of the completion of a successful call, hangs up his receiver, sending his apparatus back to normal in the manner above described.

15 The apparatus having, by the act of the calling subscriber hanging up his receiver, been returned to normal, the apparatus shown in Fig. 19 returns to normal, breaking the circuit for the release control relay 20 658 at upper right contact of 630. The relay 658 deenergizing allows its armatures to retract, and at its right armature and back contact closes a circuit to move sequence switch 660 from the fifteenth into 25 the eighteenth position, where a ground will be again found on the "Y" commutator to move the sequence switch to normal.

The call above described assumed that both the calling and called subscribers were 30 located in the same exchange, and that therefore the district and office key 379 caused the selection of "A" and "B" incoming switches to pick out the calling and called subscribers' apparatus. If, however, it is 35 desired to call from one office a subscriber located in a different office, such a district and office key of the plurality shown in Fig. 6 must be depressed that an "A" incoming 40 switch will connect with the calling subscriber in the station in which the call is initiated and extend over trunks to an incoming switch located at the station in which the subscriber wanted is located. If we assume that the calling subscriber 4342 45 desires connection with a subscriber whose number is the same as in the call just described, that is, 5682, but located in another office, we depress a district and office key, say 386, which will result in the seizing, by an office selector switch, of an "A" 50 interoffice incoming switch leading eventually to the called subscriber through the intervention of a "B" interoffice switch.

The initiation of a call under these conditions is the same as above described up to a 55 certain point, that is, the removal of the receiver by the calling subscriber operates the line switches shown in Figs. 1 and 2 until the operator's set, shown in Fig. 3, is connected over a temporary call circuit with 60 said calling subscriber. The calling subscriber's number is automatically recorded on the recorders shown in Fig. 5 and these numbers registered on the registers shown 65 in Fig. 11. The operator, as in the previous

case, learns from the subscriber the number of the line wanted, which, in this case, is the same as in the case above described but located not in the same exchange but in another exchange. She, therefore, depresses 70 a district and office key corresponding to the district and office in which the number of the called subscriber is located, and we will assume that key 386 is such a key. The depression of key 386 causes the registration 75 of the district and office corresponding thereto on the registers shown in Fig. 10. The recordation and registration of the numerical number of the calling subscriber takes place on Figs. 7, 8, and 9, as above 80 described.

The sequence switch 403 of the district and office register moved into position 2 when sequence switch 226 moved into its third position, the circuit for the sequence 85 switch 403 being closed in this position of sequence switch 226 at the lower right and left contacts of 255 to ground.

With the sequence switch 403 in the second position the depression of district and 90 office key 386 closes a circuit from battery, energizing winding of relay 453, upper left contact of 475, lower left contact of 476, energizing winding of relay 477, conductor 481, district and office key 386, conductor 95 382, energizing winding of relay 411, conductor 412, lower right contact of 413, conductor 414, lower left contact of 415, conductor 416, energizing winding of 417 to ground. 100

With the relays 411, 417 and 477 energized over the circuit traced and the relays representing the numerical numbers of the called subscriber being energized as in the first case described, the locking circuit for 105 locking all these relays up will be as follows: battery, conductor 438, locking winding of relay 436, conductor 439, conductor 440, locking winding of relay 432, conductor 441, locking winding of relay 429, conductor 442, locking winding of relay 426, conductor 443, locking winding of relay 422, conductor 444, conductor 445, locking winding of relay 477, conductor 446, conductor 447, locking winding of relay 411, 110 conductor 448, locking winding of relay 417 (at this portion of the circuit relays 411 and 417 are energized in parallel), winding of relay 256, upper left and right contacts of 257 to ground. 120

The energization of relay 256 closes at its armature and front contact a circuit leading from the armatures and front contacts of relays 449 to move sequence switch 226 from the third into the fourth position, in 125 which position a circuit is closed at the lower and upper right contacts of 257 for the knock-down relays 380 and 381 to release the keys for the district and office selector and numerical number keyboard, 130

shown in Figs. 6 and 7 respectively. Also in the fourth position of sequence switch 226 a circuit is closed for sender sequence switch 500 to move the same from the first into the 5 second position, in which position the district brush is selected in the manner heretofore described. The district brush having been selected, the sequence switch 500 moves into its fourth position to select the 10 district group. The district group having been selected the sequence switch moves into its eighth position to select the office brush and then into the tenth position to select the office group. 15 Trunk selection by the office selector switch takes place at the end of the group selection, and a trunk is selected leading to an "A" interoffice incoming switch in accordance with the number of the district 20 and office key 386 depressed.

We will assume that the trunks terminate in terminals 532, 533 and 534, and that these trunks lead to the "A" interoffice incoming switch, shown in Fig. 14. The brushes 529, 25 530 and 531 on coming into engagement with the terminals 532, 533 and 534, respectively, the circuit for relay 511 is broken, deenergizing said relay, and at its left armature and front contact breaking the circuit for 30 the up magnet 524, stopping the upward movement of the brush carriage. The relay 511 when deenergized at its left armature and back contact, closes a circuit to move sequence switch 519 from the sixth and into 35 the eighth position.

With the sequence switch 519 in the eighth position sequence switch 226 in the tenth position and the brushes of the office selector switch in contact with the terminals 40 of the trunk leading to the "A" interoffice incoming switch, shown in Fig. 14, a circuit is closed from battery, relay 582, lower left and upper right contacts of 583, conductor 602, terminal 532, brush 529, conductor 537, upper right and lower left contacts of 513, conductor 514, terminal 278, brush 275, upper left and right contacts of 263, conductor 264, upper armature and back contact of the 0' counting relay, stepping relay 503, upper right and left contacts of 504, conductor 265, lower and upper right contacts of 266, brush 276, terminal 279, conductor 515, lower and upper right contacts of 516, brush 530, terminal 55 533, conductor 603, upper right and left contacts of 584, to ground.

The relay 582 energizing, closes at its left armature and front contact a circuit for the release control relay 585 from battery, winding 60 of said relay, conductor 499, upper right and left contacts of 586, left armature and front contact of 582 to ground, energizing said relay 585 and closing a locking circuit for the same from battery, winding 65 thereof, conductor 498, terminal 534, brush

531, conductor 536, upper left and right contacts of 535, right armature and back contact of relay 511, upper and lower left contacts of 528 to ground.

The release control relay 585 when energized closes at its bottom armature and front contact a circuit which extends through the lower and upper left contacts of 587 to move sequence switch 588 from the first into the second position, and relay 582, which was 70 energized in the first position of the sequence switch by a circuit which extended through the lower left and upper right contacts of 583, has this energizing circuit broken at the lower left contact of 583 when sequence switch 588 passes out of its first position. An energizing circuit for said relay 582 is, however, maintained in the second position of sequence switch 588 from battery, winding of said relay 582, right armature and front contact thereof, upper left and right contacts of 583, and over the path traced above to ground. 80

On coming into its second position a circuit is closed for the up magnet 589 from 90 battery, winding of said magnet 589, lower right and upper left contacts of 586, left armature and front contact of 582 to ground. Brush selection now takes place, a shunt being placed on the stepping relay 503 from ground on the "A" commutator, upper right and left contacts of 590, to the energizing circuit of said stepping relay 503 at the upper left contact of 583. The brush having been selected, the relay 582 will be deenergized; the sequence switch 500 will be moved from its twelfth into its fourteenth position; sequence switch 588 will be moved into its third position, at which point the relay 582 will be again energized, on its energization 95 closing a circuit to move the sequence switch 588 from the third into the fourth position. In the third position of sequence switch 588, a circuit is closed from battery, trip magnet 497, lower left contact of 591, upper left contact of 584 to ground energizing said trip magnet, and tripping the proper set of brushes 592, 593, 594 into engagement with the bank of terminals containing the terminals of the trunk leading to the "A" final 110 switch. In the fourth position group selection takes place, the ground for shunting out the stepping relay 503 being found in this selection on the "B" commutator. As before when the proper group is selected, 115 the relay 582 is deenergized and sequence switch 588 moves from its fourth into its fifth position, with sequence switch 500 moving into the sixteenth position.

With sequence switch 588 in its fifth position, a circuit is closed for relay 582 from battery, winding of said relay 582, upper right contact of 591, upper left contact of 584 to ground, energizing said relay, and at the left armature and front contact there- 120 125 130

of closing a circuit to move sequence switch 588 into the sixth position, a circuit for the relay 582 being then from battery, winding thereof, right armature and front contact, upper left and right contacts of 590 to ground at the "C" commutator. Also at the left armature and front contact of said relay 582 a circuit is closed for the up magnet 589 and through lower right and upper left contacts of 586, energizing said up magnet and moving the brushes 592, 593, 594 over the terminal bank. When an idle trunk is found, relay 582 will be deenergized, and when the left armature thereof reaches its back contact a circuit will be closed to move the sequence switch 588 from the sixth into the seventh position, breaking the circuit through the up magnet 589 and stopping the brushes 592, 593 and 594 in engagement with the terminals 595, 596 and 597, respectively, of an idle trunk leading to the "A" final switch.

The sequence switch 500 being at this time in the sixteenth position a circuit will be closed for relay 582 as heretofore traced, energizing the same, and at its left armature and front contact closing a circuit to move sequence switch 588 out of its seventh and into its eighth position, and at the same time closing a locking circuit for itself through its right armature and front contact and over the original energizing circuit.

Sequence switch 588 being now in the eighth position, a circuit will be closed from battery, relay 588, upper and lower right contacts of 539, conductor 540, terminal 595, brush 592, upper and lower left contacts of 598, left armature and front contact of 582 to ground. The relay 588 when energized closes a circuit at its right armature and front contact and upper left and right contacts of 556 for the release control relay 555, which when energized closes a locking circuit for itself through its right armature and front contact, conductor 558, terminal 597, brush 594, lower and upper left contacts of 584 to ground.

Relay 555 when energized closes a circuit at its left armature and front contact and lower right contact of 542 to move sequence switch 541 from its first into its second position, in which position brush selection takes place in the manner above described in connection with the first call.

In the final brush selection the ground for shunting the stepping relay 503 out to cause the stepping of the brush is found from ground, the "A" commutator, upper right contact of 543, upper right contact of 544, conductor 563, terminal 596, brush 593, upper and lower left contacts of 599, joining the energizing circuit for the stepping relay 503 at the upper left contact of 583. The up-magnet 545 being energized the brush carriage moves upward and will move up-

ward in accordance with the number of counting relays energized, the stepping relay 503 being shunted out each time the brush passes off the segments of the "A" commutator. Upon moving up the required number of steps the circuit through the stepping relay 503 is permanently broken, deenergizing the relay 582, which in turn deenergizes relay 538.

The relay 582 deenergizing moves sequence switch 588 from the eighth into the ninth position, and relay 538 deenergizing moves sequence switch 541 from the second into the third position.

At the end of this selection sequence switch 500 moves from the sixteenth into the second position.

The moving of the sequence switch 500 from the sixteenth into the second position broke the circuit through the locked-up counting relays, and as the sequence switch came into the second position the proper set of counting relays was energized to cause the selection of the "A" final tens brush.

While sequence switch 500 is moving through positions seventeen and eighteen, a circuit is closed from grounded battery, power magnet of sequence switch 226, upper right contact of 281, conductor 282, upper left contact of 510, to ground, for moving sequence switch 226 out of position 10 and into position 11.

In the ninth position of the sequence switch 588 with the sequence switch 500 in the second position, the circuit through the stepping relay 503 and relay 582 is again completed energizing both these relays, the relay 582 completing a circuit to move sequence switch 588 from the ninth into the tenth position, and when moved into the tenth position transferred the energizing circuit from the winding through the lower left contact of 583 to the left armature and front contact thereof and upper left contact of 583. Also the energization of 582, with the sequence switch 588 in the tenth position, closed the energizing circuit for relay 538 at the left armature and front contact of said relay 582.

The relay 538 energizing, closed at its right armature and front contact a circuit to move sequence switch 541 out of the third and into the fourth position. In this position also, a circuit is closed for the up magnet 545 at the lower and upper left contacts 120 of 556 and the right armature and front contact of 538.

The original energizing circuit 538 is now replaced by a locking circuit extending from battery, winding of said relay 538, left armature and front contact from lower left and upper right contacts of 539, over the path of the original energizing circuit traced above. The up magnet being energized the brush starts again on its upward travel, the ground 130

for shunting out the stepping relay 503 with each step of the brush over the commutator segments being found from ground at commutator "B," upper left contact of 543, 5 upper right contact of 544, connecting with the energizing circuit of stepping relay 503 at the upper left contact of 583. The brush as before takes as many steps as there are pairs of counting relays to be energized, and 10 at the last energization of a counting relay the circuit through the stepping relay 503 and relay 582 is permanently broken at the upper armature and back contact of the 0' counting relay, causing the deenergization 15 of relay 582, which in turn, at its left armature and front contact, breaks the circuit for the relay 538.

Relay 538 deenergizing breaks at its right armature and front contact the circuit for 20 the up magnet 545, and closes at its right armature and back contact a circuit to move sequence switch 541 out of its fourth and into its fifth position.

The relay 582 on deenergizing, closed at 25 its left armature and back contact a circuit to move sequence switch 588 out of its tenth and into its eleventh position. The energization of the 0' counting relay at the end of the tens selection closes a circuit to move 30 sequence switch 500 out of its second and into its fourth position.

On passing out of the second position the circuit through the locked up counting relays was broken, and the break point in the 35 circuit for stepping relay 503 and relay 582 was closed at the left upper armature and back contact of the 0' counting relay, and a second break point in this circuit was closed when sequence switch 500 reached its fourth 40 position at the upper left contact of 504. The proper set of counting relays is now energized to cause units selection at the final switch. Immediately upon the closing of the break points in the energizing circuit 45 for stepping relay 503 and relay 582, as above described, both these relays were energized, relay 582 at its left armature and front contact closing a circuit to move sequence switch 588 out of its eleventh and 50 into its twelfth position, and when fully energized again transferring a portion of its energizing circuit from the lower left contact of 583 to the upper left contact of 583 through its right armature and front contact. When energized it also at its left armature and front contact closed the energizing 55 circuit for relay 538, which relay, at its right armature and front contact closed a circuit to move sequence switch 541 from 60 the fifth into the sixth position. The relay 538 locking up in the fifth position over circuit battery, winding of said relay 538, left armature and front contact thereof, lower left and upper right contacts of 539, over the 65 circuit traced for this relay above. At the

right armature and front contact a circuit is again closed for the up magnet 545, moving the brushes 546, 547, 548 over the bank of terminals to select the terminal of the line leading to the calling subscriber's station, 70 ground being placed on the energizing circuit of stepping relay 503 to shunt said relay once for each step of the brush over the "C" commutator, upper right contact of 543, upper right contact of 544, and joining 75 the energizing circuit of stepping relay 503 at the upper left contact of 583.

The brush will step upward in accordance with the number of counting relays energized in succession, or until the 0' counting 80 relay is energized, when the energizing circuit for stepping relay 503 is again broken at the upper armature and back contact of said 0' counting relay, deenergizing in this manner the relay 582, which at its left armature and front contact breaks the energizing circuit for the relay 538, which in turn deenergizes closing at its right armature and back contact a circuit to move sequence switch 541 from its sixth into its seventh 90 position, and at its right armature and front contact breaking a circuit for the up magnet 545, stopping the brush carriage with its brushes 546, 547, 548 in engagement with the terminals 549, 550 and 551, respectively, 95 of the calling subscriber's line. The relay 582 deenergizing, closed at its left armature and back contact a circuit for sequence switch 588, moving the same from the twelfth and into the thirteenth position. 100 The energization of the 0' counting relay on this last selection moves sequence switch 500 out of its fourth position and into its seventh position.

While sequence switch 500 is passing 105 through positions 5 and 6, a circuit is completed from grounded battery, motor magnet of sequence switch 226, lower right contact of 281, conductor 283, lower left contact of 510, to ground, for moving sequence 110 switch 226 out of position 11 and into position 12.

The sequence switch 226 being at this time in the twelfth position and sequence switch 588 being in position thirteen, a circuit is closed for relay 582 from battery, winding of said relay, lower left and upper right contacts of 583, conductor 602, terminal 532, brush 529, conductor 537, upper right and lower left contacts of 513, conductor 514, terminal 278, brush 275, upper left and lower right contacts of 263, lower left contact of 274 to ground. Relay 582 energizing closes a circuit at its left armature and front contact, to move sequence 125 switch 588 from its thirteenth into the fourteenth position.

The test relay 285, which is energized from battery through impedance 286, the listening key, out over the temporary call 130

circuit, subscribers' apparatus, back over the other side of the temporary call circuit to ground, through impedance 287, from the second to the twelfth position of sequence switch 226, is shunted out by a ground when the brushes 546, 547 and 548 come into engagement with the terminals 549, 550 and 551 respectively of the calling subscriber's line. The test relay 285 deenergizing closes 10 at its right armature and back contact and upper left contact 285 a circuit to move sequence switch 226 out of its twelfth, through the thirteenth and into its fourteenth position, and at its left armature and back contact closes a circuit to restore the line switches shown in Figs. 1 and 2 to normal, as above described.

As sequence switch 226 passed out of its twelfth position the energizing circuit for 20 relay 582 was broken at lower right contact of 263, and on this relay 582 deenergizing it closed at its left armature and back contact a circuit to move sequence switch 588 out of its fourteenth and into its fifteenth position.

In the fifteenth position of sequence switch 588 a circuit is closed from battery, one winding of repeating coil 496, winding of supervisory relay 495, upper right and 30 left contacts of 599, brush 593, terminal 596, conductor 563, upper right and left contacts of 544, brush 547, terminal 550, conductor 573, out over the calling subscriber's line, back through conductor 572, terminal 35 549, brush 546, upper left and right contacts of 539, conductor 540, terminal 595, brush 592, upper left and lower right contacts of 598, and winding of repeating coil 496, to battery. The supervisory relay 495 energizing attracts its armature, closing a circuit from battery, relay 494, armature and front contact of supervisory relay 495, to ground.

When sequence switch 226 came into its 45 tenth position a circuit is closed from battery, motor magnet of sequence switch 500, lower left contact of 501, lower right contact of 261 to ground, moving sequence switch 500 from its seventh into its eighth position.

In the eighth position of this sequence switch a break point in the energizing circuit for the stepping relay 503 is closed at the upper left contact of 504. Also the energizing circuit, in which is located the stepping relay 503, has also located therein the relay 700, the energizing circuit for both these relays being traced at this time as follows: battery, winding of said relay 60 700, lower right and upper left contacts of 701, conductor 648, upper and lower right contacts of 493, conductor 602, terminal 532, brush 529, conductor 537, upper right and lower left contacts of 513, conductor 514, 65 terminal 278, brush 275, upper left and right

contacts of 263, conductor 264, upper armature and back contact of 0' counting relay, stepping relay 503, upper left contact of 504, conductor 265, lower and upper right contacts of 266, brush 276, terminal 279, 70 conductor 515, lower and upper right contacts of 516, brush 530, terminal 533, conductor 603, lower and upper right contacts of 492, conductor 649, upper left and lower right contacts of 702, to ground. 75

Relay 700 energizing closes at its left armature and front contact a circuit from battery, motor magnet of sequence switch 703, upper left contact of 704, left armature and front contact of 700 to ground, moving sequence switch 703 from the first into the second position. The energizing circuit of 700, which in the first position of 703 passed from battery, winding of said relay 700, lower right and upper left contacts of 701, 85 passes—with the sequence switch 703 in the second position—and relay 700 energized—from battery, winding of said relay 700, upper right and left contacts of 701, over the circuit traced for said relay above. 90

In the second position of sequence switch 703 a circuit is closed from battery, up magnet 705, lower left and right contacts of 706, left armature and front contact of relay 700, to ground. The brush carriage is 95 moved upwardly due to the energization of the up magnet 705 over the "A" commutator, and a shunt to this circuit for shunting out the stepping relay 503 exists from ground at the "A" commutator, lower left and right contacts of 707, joining the energizing circuit for the stepping relay 503 at the upper right contacts of 701, this ground third position. Also it breaks a circuit whenever the brush is in engagement with 100 a segment of the "A" commutator. 105

When the counting relays have been satisfied and the 0' counting relay energized, the circuit through relay 700 is broken at the upper armature and back contact of 110 said 0' counting relay, deenergizing the same and closing a circuit at the left armature and back contact to move sequence switch 703 out of its second and into its third position. Also it breaks a circuit 115 for the up magnet 705 at its left armature and front contact, stopping the upward movement of the brush carriage. The energization of the 0' counting relay closed at its lower armature and front contact a 120 circuit to move sequence switch 500 out of its eighth and into its tenth position.

The sequence switch 500 moving out of its eighth position breaks the circuit for the locked-up counting relays, and when 125 said sequence switch reaches its tenth position it closes at the upper right and left contacts of 504 a break point in the energizing circuit for the stepping relay 503. The relay 700 which is in the circuit of the 130

stepping relay 503 is again energized as before, first through the lower right contact of 701, and when the relay is fully energized a circuit is closed at the right armature and front contact thereof and through the upper right contact of 701. A circuit is closed on the energization of relay 700 at the left armature and front contact thereof to move sequence switch 703 out of its 10 third and into its fourth position.

On coming into the fourth position the circuit for the up magnet 705 is again closed at the lower left and right contacts of 706, and left armature and front contact 15 of relay 700, energizing the same and causing the brush carriage to move upwardly. The ground for shunting out the stepping relay 503 will be found in the fourth position of sequence switch 703 through the 20 "B" commutator, upper left and lower right contacts of 707, joining the energizing circuit for stepping relay 503 at the upper right contact of 701.

In the tenth position of sequence switch 25 500, a circuit is closed to energize the proper pair of counting relays to select the proper group of terminals in the "B" interoffice incoming switch, and, as has been previously described, the stepping relay will be 30 energized and deenergized in accordance with the pair of counting relays selected, stepping the brush carriage upwardly until the proper group is selected. Also, as before, when the 0' counting relay is reached, 35 the circuit for stepping relay 503 and relay 700 is broken at the upper armature and back contact of said 0' counting relay, deenergizing both of said relays and closing a circuit to move switch 500 out of its 40 tenth and into its twelfth position.

Relay 700 deenergizing closes at its left armature and back contact a circuit to move sequence switch 703 out of its fourth and into its fifth position, and also at the left 45 armature and front contact breaks a circuit for the up magnet 705.

On coming into the fifth position a circuit is closed from battery, relay 700, lower left and right contacts of 709 to ground, energizing said relay and closing at the left 50 armature and back contact thereof a circuit to move sequence switch 703 out of its fifth and into its sixth position, a circuit for relay 700 being at this time extended from 55 battery, winding of said relay 700, right armature and front contact thereof, lower right and left contacts of 707, the "C" commutator to ground.

In the sixth position of sequence switch 60 703 with the relay 700 energized, a circuit is closed for up magnet 705 from battery, lower left and right contacts of 706, left armature and front contact of relay 700 to ground. The up magnet being energized,

the brushes 710, 711, 712 move over the 65 bank of terminals until they come into engagement with the terminals 713, 714 and 715, respectively, of an idle trunk, in which position the relay 700 is shunted out, breaking at its left armature and front contact 70 a circuit for the up magnet 705, stopping the brushes 710, 711 and 712 in engagement with the terminals 713, 714 and 715 of an idle trunk leading to the "B" final switch, and at its left armature and back contact 75 closing a circuit for sequence switch 703, moving the same from the sixth position through position seven and into position eight.

In the meantime sequence switch 500 has 80 moved from the tenth into the twelfth position due to the energization of the 0' counting relay. When it reaches its twelfth position the circuit through the locked-up counting relays is broken and the energizing circuit for stepping relay 503 and relay 700 is again completed, the circuit being through the lower right and upper left contacts of 701 in the eighth position of sequence switch 703. Relay 700 energizing 90 closes at its left armature and front contact a circuit to move sequence switch 703 from its eighth and into the ninth position. In the ninth position the circuit for relay 700 is completed at the upper right and left 95 contacts of 701.

On sequence switch 703 coming into the ninth position a circuit will be closed from battery, winding of relay 656, lower right and upper left contacts of 657, conductor 100 682, terminal 713, brush 710, upper and lower right contacts of 716, left armature and front contact of relay 700 to ground. Relay 656 energizing attracts its armatures and closes at its left armature and front contact a locking circuit for itself at the lower and upper left contacts of 657 and over the path above traced. The release control relay 658 is energized over path from battery, winding of said release control relay 658, 110 lower left and right contacts of 661, right armature and front contact of relay 656 to ground.

When release control relay 658 is energized it closes at its left armature and front 115 contact a locking circuit for itself from battery, winding of said release control relay, left armature and front contact thereof, conductor 684, terminal 715, brush 712, upper right and left contacts of 717 to ground, and at its right armature and front contact closes a circuit for sequence switch 660 to move the same from the first into the second position, in which position a circuit is closed from battery, up magnet 662, upper 120 and lower right contacts of 659, right armature and front contact of 656 to ground.

With the sequence switch 660 in the sec-

second position and the up magnet 662 energized, sequence switch 703 in the ninth position and sequence switch 500 in the twelfth position, a circuit is closed from battery to ground at the stepping relay 503 through the proper set of counting relays to determine the "B" final brush to be selected. In addition, the stepping relay 503 and relay 700 are energized in series, and in the second position of sequence switch 660 ground will be found on this circuit to shunt out the stepping relay 503 from ground at the "A" commutator, lower right and upper left contacts of 663, conductor 683, terminal 714, brush 711, upper left and right contacts of 718, joining the energizing circuit for the stepping relay 503 at the point 719. The brush carriage moves upwardly, the stepping magnet 503 being shunted out by ground from the "A" commutator with each step of the brush. The brush moves upwardly as many steps as there are pairs of counting relays energized, in the manner now well understood, until the 0' counting relay is energized, at which time the circuit through the stepping relay 503 is broken at the upper armature and back contact of said 0' counting relay, deenergizing the relay 700, which at its left armature and back contact closes a circuit to move sequence switch 703 out of the ninth and into the tenth position. In passing out of the ninth position sequence switch 703 broke, at the lower right contact of 716, the energizing circuit for relay 656, which relay is in turn deenergized, and at its right armature and front contact breaking the circuit for the up magnet 662 and at its right armature and back contact closing a circuit to move sequence switch 660 from the second into the third position. On the energization of the 0' counting relay a circuit is closed at the lower armature and front contact thereof to move sequence switch 500 from the twelfth and into the fourteenth position, in which position the circuit for the stepping relay 503 and relay 700 is again closed at the upper armature and back contact of the 0' counting relay and the upper right and left contacts of 504, energizing relay 700 and stepping relay 503 in series over the path above traced, and placing ground at the armature and front contact of stepping relay 503 from battery, through the proper pair of counting relays, to insure the selection of the tens brush in the final switch. Relay 700, being energized, attracts its armatures, and at its left armature and front contact closes a circuit to move sequence switch 703 from the tenth into the eleventh position, and in the eleventh position energizing the relay 700 over the circuit extending not through the lower right contact of 701 but through the upper right contact.

Sequence switch 703 being now in the eleventh position a circuit will be again closed for relay 656 at the upper and lower right contacts of 716 and left armature and front contact of relay 700, energizing said relay 656, and when the relay is fully energized transferring the circuit thereof from battery, winding of the relay, lower right and upper left contacts of 657, over the path above traced to the circuit: battery, winding of said relay, left armature and front contact thereof, lower and upper left contacts of 657, and over the original path traced.

Relay 656, when energized, closes at its right armature and front contact a circuit to move sequence switch 660 from the third into the fourth position, and also at the same armature and contact and lower and upper right contacts of 661 closes a circuit for the up magnet 662, moving the brush carriage upwardly over the "B" commutator.

Sequence switch 500 being now in the fourteenth position, sequence switch 703 in the eleventh position, and sequence switch 660 in the fourth position, the relay 700 and stepping relay 503 are energized in series, and a ground exists from "B" commutator, lower and upper left contacts of 663, conductor 683, terminal 714, brush 711, upper right and left contacts of 718, joining the energizing circuit for stepping relay 503 at the point 719, resulting in the shunting out of the stepping relay each time the brush contacts with a segment of the "B" commutator. The stepping relay being energized at its armature and front contact, places a ground from battery on the proper pair of counting relays to cause tens selection.

The stepping relay is alternately deenergized and energized as the brush moves over the segments of the "B" commutator until, as has been above described, the 0' counting relay is energized, at which time the circuit for stepping relay 503 and relay 700 is broken at the upper armature and back contact of the 0' counting relay. Relay 700 being deenergized closes at its left armature and back contact a circuit to move sequence switch 703 out of the eleventh and into the twelfth position, breaking the circuit for the relay 656 at the lower right contact of 716.

Relay 656 deenergizing, closes at its right armature and back contact a circuit to move sequence switch 660 out of the fourth and into the fifth position, and also breaks at the same armature and front contact the circuit for the up magnet 662, stopping the upward movement of the brush carriage.

The energization of the 0' counting relay closes a circuit for sequence switch 500, moving the same from the fourteenth into the sixteenth position, breaking the circuit through the locked-up counting relays, and

allowing the same to deenergize, the 0' counting relay, on the retraction of its armatures, closing the break points in the energizing circuit for the relay 700 and stepping relay 503.

5 The sequence switch 500 on coming into the sixteenth position completes the energizing circuit for stepping relay 503 and relay 700 at the upper left contact of 504, energizing both these relays in series, the stepping relay 503, at its armature and front contact, placing a ground from battery on the proper pair of counting relays to select the terminals of the called line. Relay 700 when energized, closes at its left armature and front contact a circuit to move sequence switch 703 from the twelfth into the thirteenth position, in this position maintaining the energizing circuit for itself closed at the upper 10 right contact of 701. Also the relay 700 being energized, closes at its left armature and front contact a circuit for relay 656, which extends as heretofore traced through the upper and lower right contacts of 716. Relay 656 energizing, closes at its right armature and front contact a circuit to move sequence switch 660 out of the fifth and into the sixth position, and in this position maintaining its energizing circuit closed at the 15 lower and upper left contacts of 657.

On coming into the sixth position a circuit is closed for the up magnet 662 from battery, winding of said magnet, upper and lower right contacts of 661, right armature and front contact of relay 656 to ground. In this position of sequence switch 660 a ground will be found from the "C" commutator through the lower right and upper left contacts of 663, through the circuit heretofore traced, and joining the energizing circuit for relay 700 and stepping relay 503 at the point 719. The brushes move upwardly due to the energization of the up magnet 662, and the stepping relay 503 is alternately energized and deenergized in accordance with the number of pairs of counting relays energized, the brushes taking as many steps as there are pairs of counting relays selected on until the 0' counting relay is energized, 20 at which time the stepping relay 503 will have its energizing circuit broken at the upper armature and back contact of the 0' counting relay, and the brushes 669, 670 and 671 will be in engagement with the terminals 55 672, 673 and 674 respectively of the called line.

The breaking of the circuit of the stepping relay 503 and relay 700 at the upper armature and back contact of the 0' counting relay caused the deenergization of the relay 700, which at its left armature and back contact closed a circuit to move sequence switch 703 out of the thirteenth and into the fourteenth position, breaking at the lower right 65 contact of 716 the energizing circuit for re-

lay 656, which in turn at its right armature and front contact broke the circuit for the up magnet 662, and at its right armature and back contact closes a circuit for sequence switch 660, moving the same from the sixth 70 into the seventh position.

The energization of the 0' counting relay closed at its lower armature and front contact a circuit to move sequence switch 500 from the sixteenth and into the first or 75 normal position.

As the sequence switch passes through the seventeenth and also the eighteenth position, a circuit is closed for sequence switch 226 from battery, motor magnet of said sequence switch, conductor 227, upper right contact of 281, conductor 282 upper left contact of 510 to ground, moving the sequence switch from the fourteenth into the fifteenth position.

On coming into the fifteenth position a circuit will be closed to ground at the upper left contact of 255 and the contacts of 290' for sequence switch 402 of the thousands, hundreds, tens and units registers of the lines as calling lines, moving said sequence switches from the position in which they now stand through the eighteenth and into the normal position.

Also in moving out of the fourteenth position sequence switch 226 broke the energizing circuit for relay 256 at the upper left contact of 257, destroying the locking circuit for the locked-up register relays of the district and office thousands, hundreds, tens and units registers shown in Figs. 10, 8 and 9.

With relay 256 deenergized and sequence switch 226 in the fifteenth position, a circuit is closed from battery, motor magnet of sequence switch 226, conductor 227, upper right contact of 228, armature and back contact of 256, lower left and right contacts of 288, conductor 579, lower left and upper right contacts of 482 of the thousands, hundreds, tens and units registers of the lines as calling lines to ground, moving sequence switch 226 from the fifteenth, through the sixteenth, seventeenth and into the eighteenth position.

In the eighteenth position a circuit is closed at lower right and left contacts of 273 for the down magnet 290, and the brush carriage is moved downwardly until the Y commutator is reached, at which time a circuit will be closed at the lower left contact of 281 to move sequence switch 226 from the eighteenth and into its first or normal position.

As the sequence switch 226 moves out of its sixteenth position the locking circuit for release control relay 517 is broken at the upper right contact of 274. The relay 517 is therefore deenergized, and at its right-hand armature and back contact closes a circuit 130

for sequence switch 519, moving the same from its eighth and into its seventeenth position, at which time a circuit will be closed at the lower right and left contacts of 528 for the down magnet 580. The brush carriage therefore moves downwardly until the Y commutator is reached, at which time a circuit will be closed to ground for the sequence switch 519, moving the same from its seventeenth and into its first or normal position.

As sequence switch 519 moved out of its ninth position the holding circuit for release control relay 585 is broken at the upper left contacts of 525 and 528, respectively. The release control relay 585 is therefore de-energized, and at its lower armature and back contact and upper right contact of 587 closes a circuit for sequence switch 588, moving the same from the fifteenth into the sixteenth position.

On sequence switch 588 coming into the sixteenth position a circuit will be closed from battery, one winding of repeating coil 496, supervisory relay 487, lower armature and front contact of relay 494, lower left and upper right contacts of 492, conductor 649, lower left winding of repeating coil 726, the high-resistance winding of 720, lower left and upper right contacts of 721, upper left winding of repeating coil 726, conductor 648, upper right and left contacts of 493, upper armature and front contact of relay 494, upper right winding of repeating coil 496, to ground. Supervisory relay 487 is energized in this circuit, attracting its armature and closing a circuit from battery, motor magnet of sequence switch 588, lower right contact of 486, armature and front contact of supervisory relay 487 to ground, moving sequence switch 588 from its sixteenth into its seventeenth position.

Also in the circuit above traced the relay 720 is energized, closing a circuit from battery, relay 700, lower left and upper right contacts of 709, armature and front contact of relay 720 to ground, energizing said relay 700, which at its left armature and front contact closes a circuit for sequence switch 703, moving the same from its fourteenth into its fifteenth position, and in the fifteenth position closing a circuit from battery, ringing control relay 722, upper and lower right contacts of 706, left armature and front contact of relay 700 to ground.

Sequence switch 703 coming into the fifteenth position a circuit is closed from battery, winding of relay 656, lower right and upper left contacts of 657, conductor 682, terminal 713, brush 710, upper right and lower left contacts of 716, to ground, energizing relay 656, which at its armature and front contact closes a circuit to move sequence switch 660 from its seventh into the eighth or testing position. The brushes 669,

670 and 671 being at this time in engagement with the terminals 672, 673 and 674 respectively, of the wanted line, if said wanted line is idle, an energizing circuit will be found for relay 665 from the substation, through upper left and lower right contacts of 664, lower winding of relay 665, lower right and upper left contacts of 666, upper winding of relay 665 to ground, energizing the same and causing it to attract its armatures, the lower armature and front contact providing a path through the lower winding for a locking circuit, keeping said relay 665 energized and making the line busy to any other line testing the same.

A circuit will be provided in the eighth position of sequence switch 660 at the upper right contact of 696 and the upper armature and front contact of relay 665 to move sequence switch 660 from the eighth into the tenth position.

On coming into the tenth position a circuit will be closed at right armature and back contact of relay 656 to move sequence switch from the tenth into the twelfth position, in which position another circuit will be found closed at the upper right contact of 696 and the upper armature and front contact of relay 665 to move sequence switch 660 from the twelfth into the fourteenth or talking position.

On the arrival of sequence switch 660 into the fourteenth position a circuit will be found from the ringing device through relay 723, armature and front contact of ringing control relay 722, lower and upper right contacts of 718, brush 711, terminal 714, conductor 683, upper left and right contacts of 680, brush 670, terminal 673, conductor 693, out through the called subscriber's apparatus, back through conductor 694, terminal 674, brush 671, upper right and left contacts of 657, conductor 682, terminal 713, brush 710, upper right and lower left contacts of 716 to ground. Current from the ringing device is projected over the circuit traced and operates the signaling device at the called subscriber's substation. When the called subscriber removes his receiver from the switchhook the relay 723 in the ringing circuit above traced operates, attracting its armature and closing a circuit for sequence switch 703, moving said sequence switch from the fifteenth into the sixteenth or talking position.

Conversation now takes place between the two subscribers, the apparatus in use during this connection being shown in Figs. 15, 14, 16 and 17; all other apparatus and circuits shown being in the normal position and in condition to be used by any succeeding call.

The conversation continues until the hanging up of the receiver of either the calling or called subscriber. As in the previous case described, we will assume that the calling

subscriber hangs up his receiver first. The hanging up of the receiver by the calling subscriber deenergizes supervisory relay 495, which, when its armature is retracted, 5 closes a circuit for sequence switch 588, moving the same from the seventeenth into the eighteenth position, in which position a circuit is closed for the down magnet 489, causing the movement of the brush carriage 10 downwardly until the Y commutator is reached, in which position a circuit is closed, moving sequence switch 588 from its eighteenth into the first or normal position.

As sequence switch 588 moves out of its 15 seventeenth position the circuit for supervisory relay 487 is broken not only at the contacts of the relay 494 but also at the upper left contact of 493, and lower left contact of 492. Also the opening of these contact points deenergizes the relay 720, breaking the circuit for relay 700, which deenergizes, and at its left armature and back contact closes a circuit for sequence switch 703, moving the same from the sixteenth through 20 the seventeenth position and into the eighteenth position, in which position a circuit is closed for the down magnet 725, causing the downward movement of the brush carriage which continues until the Y commutator 25 is reached, when a circuit is closed to move sequence switch 703 out of the eighteenth and into the first or normal position.

The apparatus shown in Fig. 17 now awaits the hanging up of the receiver by the 30 called subscriber, when the apparatus shown in said figure is returned to its first or normal position in the manner heretofore described.

We have assumed that the party called is 35 on the regular or ordinary line. If now we assume that the party wanted is the private branch exchange subscriber, when the apparatus shown in Fig. 17 comes into the eighth position and the first trunk leading to the 40 private branch exchange is busy, the relay 665 is not energized and therefore the relay 656 is maintained energized, moving sequence switch 660 through the eighth and into the tenth position.

50 In the tenth position of sequence switch 660, with the relay 656 energized, a circuit is closed for the up magnet 662 to move the brushes over the private branch exchange trunks in search of an idle trunk.

55 From the ninth to the tenth position of sequence switch 660 the private branch exchange magnet 678 is energized from battery to ground at the lower and upper right contacts of 679. The up magnet 662 being 60 energized the brushes move up over the private branch exchange trunks in search of an idle set of terminals. When the idle set is reached circuit will be closed for the magnets 678 and 665 in parallel, deenergizing 65 the relay 656 and stopping the upward move-

ment of the brushes. The relay 656 deenergizing closes at its right armature and back contact a circuit to move sequence switch 660 out of the tenth and into the twelfth position, in which position a circuit will be 70 found closed at the upper right contact of 696 to move sequence switch 660 from the twelfth into the fourteenth or talking position. The call from this point on proceeds as in the case of an ordinary call, as 75 above described.

What is claimed is:

1. In a telephone system, an exchange, a calling and a called line terminating thereat, registering devices, automatic means for setting certain ones of said registers, a link circuit and directly controlled switches connected to the ends thereof, said switches being controlled by said registering devices and operating to seize first the calling line 80 and second the called line, whereby talking connection is established therebetween.

2. In a telephone exchange system, a calling line, a central office, means thereat for automatically recording and registering the 90 number of said calling line, an interoffice trunk, and automatic switching devices directly operated in accordance with the registration of the calling line, whereby a talking circuit is established between said 95 interoffice trunk and said calling line.

3. In a telephone exchange system, a central office, a calling and a called line, a plurality of operators' positions at the central office, interoffice trunks at the central office 100 accessible to each of the plurality of operators' positions, and directly controlled automatic switches for seizing and appropriating for use an idle one of said interoffice trunks, and directly operated 105 switches at the ends of the trunk, one operating to establish connection with the calling line and the other to establish connection with the called line.

4. In a telephone exchange system, a calling and a called line, means for establishing a talking circuit between said lines, said means including directly controlled selector switches which are restored to normal position when the talking circuit between 110 the lines is established and a link circuit having directly controlled switches connected to the ends thereof, operating to seize first the calling line and second the called line.

5. In a telephone exchange system, a calling and a called line, a central office, automatically adjusted registering devices thereat, automatic means for setting certain ones of said registering devices and automatic 125 switches directly controlled by said registering devices to connect with said calling line and said called line to establish talking connection between said lines.

6. In a telephone exchange system, the 130

- combination with a central office having an operator's position and a register individual thereto, of a substation line extending to said central office, a temporary calling circuit for extending said substation line to said operator's position, means independent of said temporary calling circuit for extending the substation line to said operator's position, means for automatically registering the number of said substation on said register, interoffice trunks and automatic switches directly operated in accordance with the number of the calling substation registered on the said register, whereby a talking circuit is established between said interoffice trunk and the calling line, which talking circuit is independent of the circuits extending to the operator who answered the call.
20. 7. In a telephone exchange system, subscribers' lines, primary and secondary line switches for extending any one of said subscribers' lines to an operator's position, means operated by said primary line switch for extending any one of said subscribers' lines to a recording device simultaneously with the extension of said line to the operator's position, said recording device comprising means for recording automatically the numbers of said subscribers' lines, means under the control of the operator for recording the number of a wanted subscriber's line, registering devices for automatically registering the numbers of the calling and called subscribers' lines, selector switches, a sending device for selectively operating said selector switches in accordance with the number of the called subscriber's line on the registers, whereby connection is established between said subscribers, and means for automatically returning said selector switches and said primary and secondary line switches to normal upon completion of the connection between said subscribers.
45. 8. In a telephone system, a central office, a sectional recorder, a register sender and directly controlled switches thereat, a plurality of subscribers' lines adapted to be seized by said directly controlled switches, a call wire for extending the lines to an operator, a line relay individual to each subscriber's line and adapted to connect the subscriber's line with the call wire, means operated, upon the seizure of the call wire, for operating the sectional recorder in accordance with the calling line number, said register sender operating, upon completion of the registration of the calling line number, to control said directly controlled switches whereby the calling line will be extended through said switches.
55. 9. In a telephone system, calling and called lines arranged in groups, a central office; a recorder, register sender and directly controlled switches thereat; a call
- wire for each group of lines extending from the group to an operator, a line relay individual to each line and adapted, when the line is a calling line, to connect said line to the call wire of the corresponding group, means operated, upon the connection of the calling line to an operator, for causing the recordation of the calling line number on the recorder, means for registering the number of the calling and called line on said register sender, said register sender operating, upon completion of the registration of the calling and called line numbers, to control said directly controlled switches, whereby the same will connect first with the calling line, and second, with the called line, and means operating, upon completion of the switching operation, to disconnect said call wire and recorder from the calling line.
10. In a telephone system, a central office, recording mechanism thereat, a calling and a called line, a temporary call circuit extending from the calling line to an operator, register mechanism at the central office on which the number of the calling line may be automatically registered and the number of the called line manually registered, a sender mechanism operating in accordance with the registration of the calling and called lines on the register mechanism, a trunk having directly controlled switches at the ends thereof, other directly controlled switches controlled by said sender mechanism and operating to control said switches connected to said trunk, one of said last named switches operating in the direction of the calling line and the other in the direction of the called line to establish connection between said lines.
15. 11. In a telephone system, a central office, directly controlled switches thereat, calling and called lines, a plurality of trunks at said central office having access to the calling and called lines, means for operating said directly controlled switches for selecting an idle one of said trunks, and switches at the ends of the selected trunk operating to seize the calling and called lines and establish talking connection therebetween.
20. 12. In a telephone system, a central office, directly controlled switches thereat, calling and called lines, a plurality of trunks at said central office having access to the calling and called lines, means for operating said directly controlled switches for selecting an idle one of said trunks, switches at the ends of a selected trunk operating to seize the calling and called lines and establish talking connection therebetween, and means for sending the directly controlled switches to normal position when the talking connection is established.
25. 13. In a telephone system, a central office,

directively controlled switches thereat, calling and called lines, a plurality of trunks at said central office having access to the calling and called lines, means for operating said directly controlled switches for selecting an idle one of said trunks, a switch at one end of a selected trunk operating to search for the calling line, and a signal de-

vice at the central office operating upon the failure of the trunk switch to find the calling line. 10

In witness whereof, I hereunto subscribe my name this 4th day of September A. D., 1915.

ALFRED H. DYSON.
